UNITED STATES PATENT OFFICE.

DARIEN W. DODSON, OF HARTFORD, CONNECTICUT, ASSIGNOR TO THE AMERICAN TYPE-BAR MACHINE COMPANY, A CORPORATION OF WEST VIRGINIA.

MACHINE FOR FORMING CHARACTERS.

No. 911,954.

Specification of Letters Patent.

Patented Feb. 9, 1909.

Application filed July 22, 1896. Serial No. 600,151.

To all whom it may concern:

Be it known that I, DARIEN W. DODSON, a citizen of the United States, residing in Hartford, in the county of Hartford and State of Connecticut, have invented certain new and useful Improvements in Machines for Making Characters, of which the following is a specification.

This invention relates to machines for making characters, letters, figures, designs, die faces or other marks on a surface, in cameo or in intaglio, raised or indented, and in the particular embodiment thereof herein illustrated and described the same is disclosed in a type-making machine, or more specifically a machine for making typebars or linotypes having each a series or line of selected or composed types integrally connected with each other and adapted for making a corresponding series or line of composed and printed characters. Since the art of mechanical type-composition was first introduced, many methods have been employed for obtaining a series of closely related printing surfaces suitable for the production of printed impressions. All of the principal methods heretofore developed may be divided into three main classes: first, those in which previously-formed, solid types are selectively assembled to form a line comprising a plurality of separate elements, from which, when properly locked up in a form, an impression may be taken; second, those in which punches, or stamps, having thereon characters in relief, or cameo, are selectively assembled in line and an impression in intaglio subsequently made in a suitable matrix material, such as papier-mâché, wood or soft metal, to obtain therein a matrix, from which a stereotype, electrotype or similar body, having a printing surface in cameo, may be formed; and third, those in which matrices having therein characters in indentation, or intaglio, are selectively assembled in line and a series of types having printing surfaces in relief, (the so-called linotype), is produced by admitting, or forcing, molten metal into a mold-box, surrounding the series of aligned characters in the matrices, or else individual types are formed from these selected matrices separately and in a similar manner.

It will be obvious that a machine adapted for carrying out a method included in the

first-mentioned class is simply an automatic type-setting or composing machine, and is not, in any sense, a type-making or type-producing apparatus.

In machines constructed for operation in accordance with a method included under the second of the before-mentioned classes, it is necessary to not only perform the operation of composing the several lines of matter, but also to obtain in the machine a matrix, or impression, of the composed line, before a printing surface can be formed by the usual methods of stereotyping, electrotyping, etc.

Up to the present time machines adapted for carrying out a method included in the third-mentioned class have attained the greatest commercial success, but in this species of apparatus, as in nearly all other type-composing machines, there is always present the objectionable feature of having to first compose, and subsequently distribute, a vast number of separate and individually-characteristic members or matrices; while the additional operations, incident to the melting and casting of type-metal, decrease the efficiency, and increase the cost of operation, of the machine. Moreover, the poisonous fumes from the melting pot of such machines, and the excessive heat emitted thereby, are injurious to health and impair the efficiency of the operator.

Many efforts have also been made to obtain a typebar embodying an integral line of types by the direct action of matrices upon type formable material located along the edge of a single piece typebar-blank, or in a blank separate from the typebar body or type-support. These have heretofore been unsuccessful owing to a variety of causes, the principal one of which is that up to the present time there has been no proper recognition of the part played by the stock of the blank lying between, and which is in excess of that necessary to form adjacent raised characters separated by intervening depressions extending below the plane of the impression faces of the types. The presence of this surplus stock obstructs in attempting to produce types located in close succession, the formation of a succession of closely related, integrally connected and satisfactory type-like characters in the face of an elongated, narrow blank, as it is practically im-

possible, under the conditions inherent in the characteristics of such a blank, especially as regards its dimensions and nature, to compress the blank sufficiently to form 5 clear cut and satisfactory printing characters, without causing the flowage of the material during the making of a character to interfere with and distort the next adjacent and finished character.

10 I have found that by adopting means for modifying or controlling in a proper manner the flowage induced by each type-making die during the working thereof, type or other characters may be made in close succession, so that the action of forming a character will not interfere with those previously made. As one means for effecting such modification or control, I provide a space or spaces by the removal of material at 15 proper points along the edge of the blank towards and into which that particular flowage occurring at each type-forming operation and tending to most detrimentally effect a finished type (that is, the flowage 20 lengthwise of the series of types to be formed) may be received without changing the position in any way of a finished type. The location of these spaces, which are preferably made along the blank progressively 25 as regards the series thereof, with the making 30 of the consecutive types, is determined by the positions which the characters are to occupy, the location of such flowage controlling or flowage receiving spaces coinciding with the location of the character-separating and word-separating spaces, and each being of such width as to enable it to 35 properly perform its function as an overflow region. In the event that such a space 40 is made forwardly of the particular portion of the blank to be operated upon prior to such operation, a type-blank will be set off from the main body of the blank. Such 45 flowage spaces may be made in any appropriate manner; but they are conveniently produced by transversely slotting the edge of the blank.

50 In making characters of different widths (a variability which will, in general, be the case) along a typebar or other blank, the length of each type-forming portion of the blank should, of course, be proportionate to the width of the character to be formed thereon in order that a printed line of composition 55 may be produced having a satisfactory appearance.

Another object of my invention is to furnish, therefore, a variable feed mechanism (herein shown as a blank-feeding mechanism) 60 adapted to feed the typebar-blank a length appropriate to the width of the selected type or other character, design or stamp to be formed. As a great variety of characters of varying contours, and especially characters having faces of varying

lengths and widths, is employed in the art of printing, I find it advantageous, and herein there exists a further feature of my invention, to remove a part or parts of the face of the type-forming portions of the 70 blank in order to shape the respective portions to a form approximating more or less closely to the type-blocks to be made therefrom. This further removal of unusable material constitutes an additional step involved in the general preliminary treatment 75 to which the typebar or other blank is subjected, and is effected where the conditions are such as to render its employment of advantage. The part or parts removed will therefore correspond in position and substantially in size with the part or parts unnecessary for the building up of the type blocks. Means are provided for this purpose comprising appropriate instrumentalities for facing one or more of the upper edges or corners of some at least of the successive portions of the blank prior to the formation of characters therein or thereon. I prefer to so face these edges of the blank 90 that the areas of the upper faces of the respectively trimmed portions will closely approximate to or be relatively small as compared with the areas of such respective faces after the corresponding impressions have 95 been formed in the blank.

It is to be understood, however, that my invention is not limited to the art of printing, as it is adapted for the production of various articles provided with a character, 100 die, design or other distinguishing mark or stamp or a plurality of the same.

A further important object of my invention is to furnish, in connection with several corresponding series of trimming and shaping tools, means for selectively actuating a corresponding tool or instrumentalities of each series into engagement with the edge of the blank, to form in the face of said blank a character, design, stamp, impression or mark of any kind corresponding to the tools selected.

In making a type or series of the same to form a type-bar, I provide means, in carrying my present invention into practice, 115 for subjecting the material of the blank to the rolling treatment of a die or series of the same successively and selectively brought into position to cooperate with the blank. Since it is contemplated that such rolling 120 shall preferably take place crosswise of the blank, the movement of the excess or unused material is naturally in the same direction. If, therefore, the blank is slotted, both the mode of operating the die and the blank, the one relatively to the other—that is to say, the crosswise rolling of the blank—and the conformation of the blank employed—that is to say, a blank having a flowage space 125 adjacent to the type to be formed—are such 130

as are well adapted to preserve the integrity of an adjacent type as a satisfactory printing member for the purposes of the art.

An operative machine for manufacturing a line of type comprising a series of closely contiguous word-related printing members such as the present invention is susceptible of embodiment in, and one form and construction of which is disclosed in the drawings attached to the present specification, is therefore one capable of applying in succession the individuals of a series of selective dies to the edge of the blank and rolling the same thereacross. Each individual die as it impinges against the blank at the proper point thus acts to crush down the material thereof and momentarily subject such material to a working. This working necessarily involves the dislodgment and shifting of relatively small quantities of material lying in the edge of the blank until, when the die leaves the blank, the type lines appear thereon. As is well known, the generation of sensible heat accompanies and naturally attends the working of metal and each die during the period it impinges against and rolls over the blank thus becomes an instrumentality for generating heat in the blank. The tendency of this generated heat to facilitate the production of the successive types by reducing the molecular or internal cohesion of the metal, is augmented by the fact that such heat at the instant of generation is localized within comparatively narrow limits—that is to say, within the mass of material in and immediately adjacent to the working die—thus raising the temperature of that portion to a higher degree than if the heat were distributed through a larger mass.

In the practical use of a working machine, the successive application of successively selected dies partakes of the nature of oft repeated blows applied to an object with the result of augmenting the temperature thereof. As the present machine is adapted to operate at comparatively high speed, the blank is subjected to a rapid succession of blows, each of which contributes its quota of heating effect confined at the instant of production to the small mass being wrought to shape. The heat thus localized at the instant of generation being confined to the mass under process of working by the heat-generating die, operates at the instant of working to the best advantage by lessening as far as may be, the rigidity of the mass in and immediately adjacent to the die without producing a similar effect in the mass of the blank lower down, and which should manifestly maintain its maximum rigidity or solidity, to best withstand the formative stresses of the working die. A machine constructed according to the present invention will therefore embody, in combination with

means for bringing a selected impression device to the working point of the machine, means for effecting a working movement between the selected impression device and a blank at such working point to progressively vary the angular relation of the impression device and the blank during the progress of the impressing of the blank.

The present machine provides a means for making types and lines of types according to the method set forth in my companion application, Serial No. 600,152, filed on even date with the present one.

In the drawings accompanying this specification, Figure 1 is a left-hand elevation, partly in section, of a machine, illustrating one embodiment of my invention. Fig. 2 is a plan of the same, partly in section. Fig. 3 is a right-hand, end elevation of a portion of the same, also partly in section. Fig. 4 is a rear elevation of the right-hand side of the machine, with parts broken away to show the construction. Fig. 5 is a transverse section of the machine, on line *a*—*a*, Fig. 3. Fig. 6 is a detail, sectional view of the adjusting means for the gear segments, (hereinafter referred to) which segments serve to lock the revolving tool-carrying shafts against slipping while the tools are operating upon the blank, the section being taken on line *b*—*b*, Fig. 7. Fig. 7 is a detail, sectional, front elevation of the same. Fig. 8 is a transverse section of the movable blank-sustaining means herein shown as a blank-carrier with certain connected devices, the section being taken on line *c*—*c*, Fig. 5. Fig. 9 is a sectional elevation of a portion of the right-hand end of the machine, showing the variable-stroke feed-mechanism (hereinafter described) in its inoperative position. Fig. 10 is a similar view, showing said feed-mechanism in its operative position. Fig. 11 is a detail, transverse section, taken on line *d*—*d*, Fig. 5, and looking from the left-hand end of the machine, showing the driving-gears for actuating the forming tools. Fig. 12 is a detail, transverse section, taken on line *d*—*d*, Fig. 5, and looking from the right-hand end of the machine, parts to the right of the plane indicated by that line being also shown and comprising the driving gears for actuating the forming tools, and other parts certain of which are broken away to show the rock-arm and plunger of the variable-stroke feed-mechanism. Fig. 13 is an enlarged, sectional, end elevation of the turret-mechanism, (hereinafter described) looking from the left-hand end of the machine. Fig. 14 is a side elevation of the same, partly in section, and illustrates the parts in the positions in which they are shown in Fig. 13. Figs. 15 to 20, inclusive, are left-hand, end elevations of the turret-mechanism and adjacent coöperating devices, and illustrates successive steps in the operation

of forming a character. Fig. 21 is an enlarged, detail, sectional elevation, looking from the left-hand end of the machine, of the coupling mechanism for operatively connecting the turret-mechanism with its driving, internal gear, and showing the parts in positions which they assume just after the uncoupling operation has occurred but before the parts have assumed their normal position, assured by the striking of a movable cam against a certain abutment. Fig. 22 is a detail, sectional view of the same, the section being taken on line $e-e$, Fig. 21. Fig. 23 is a detail, sectional elevation corresponding with Fig. 21, and shows the parts in the positions which they assume at the moment of coupling. Fig. 24 is a detail, sectional view of the same, the section being taken on line $f-f$, Fig. 23. Fig. 25 is a right-hand, end elevation of the main spur-wheel, or pinion, and its coupling and uncoupling cams. Figs. 26 to 29, inclusive, are enlarged, detail, sectional elevations, looking from the left-hand end of the machine, of the starting-arm of the turret-mechanism, and the latches and operating mechanism coacting therewith, and illustrate successive steps in the operation of starting the shaping tools carried by the turret-mechanism. Figs. 30 to 32, inclusive, are diagrammatic views, illustrating, respectively, the operation of the side-cutting tools and the die for forming a character. Fig. 33 is a detail view, illustrating in plan, and in end and side elevation, the operation of a slot-forming reducing tool, for setting off a segment of a typebar or other blank. Figs. 34 and 35 are similar views, illustrating, respectively, the operation of two side-cutting reducing tools, for facing opposite side edges of the blank. Figs. 36 and 37 are, respectively, end and side elevations, illustrating the operation of a cleaning or shaving tool for removing burs and shaving the face of the blank. Fig. 38 is a detail view, corresponding with Fig. 33, and illustrates the operation of the impressor, or character-forming, die. Fig. 39 is a detail, side elevation, and illustrates the operation of a shaving-tool for shaving the face of the finished character. Figs. 40, 41 and 42 are detail views, in plan and in side and end elevation, respectively, and illustrate the operation of a pair of cutters, for trimming the sides of the finished character to remove surplus metal. Fig. 43 is an enlarged plan of a portion of a bar-blank, illustrating the operation of different species of side-cutting reducing-tools, for facing the edges of successive character-blanks, and also illustrating the slotting of the type-bar-blank whereby there are formed character-blanks of different widths. Fig. 44 is a plan of the same, showing the result of the action of the character-forming dies or impressors consisting in the spreading of the

upper portions of the respective blanks both laterally and longitudinally of the typebar-blank and causing the filling to a more or less extent of the transverse slots in the bar-blank by the displacement or flow of the metal lying in the faces of the character-blanks. Figs. 45 and 46 are side elevations corresponding, respectively, with Figs. 43 and 44. Figs. 47, 48, 49, and 50 are cross-sectional views, the sections being taken, respectively, on lines $g-g$, $h-h$, $i-i$, and $j-j$, of Fig. 45, and illustrate, respectively, the action of different side-cutting reducing-tools for facing the edges of the character-blanks to a greater or less extent. Figs. 51, 52, 53, and 54, are cross-sectional views, the sections being taken on lines $k-k$, $l-l$, $m-m$, and $n-n$, Fig. 46, and illustrate, respectively, the operation of the several forming dies upon the blanks, indicated in Figs. 47 to 50, respectively.

Similar characters designate like parts in all the figures of the drawings.

I may make use of any suitable framework for the purpose of operatively mounting the several mechanisms and devices necessary for carrying out my invention. I have shown herein, a base-plate 2 having supporting legs or feet; and a main frame 3 and an end frame 4 are shown, as fixedly secured to said base-plate,—in the present case by suitable bolts. The main-frame or upright 3, in the form thereof herein illustrated, is provided with a substantially circular opening and has a transversely-disposed cross-piece or strengthening member 3'', provided with a bearing 3', for carrying one end of the main driving-shaft 5 of the machine, the other end of such shaft being illustrated as journaled in a corresponding bearing 4', formed in the upper side of the end frame or standard 4 and in alinement with the bearing 3'. As before stated, the invention is not limited to the manufacture of type or printing characters, although the machine is shown as organized for the production of typebars or linotypes.

As previously set forth, the general process of making, according to the present invention, integrally-connected composed types from type-formable material under the conditions as respects the permissible width of a blank which can ordinarily be used, the close proximity of contiguous types one to the other, etc., prescribed by the typographic art, involves the preparation of consecutive portions of the edge of the blank which results in so modifying and controlling the flowage induced by the working character-forming or type-making instrumentality when brought into operation, as to render it possible to make composed, integrally-connected types without displacing or in any wise distorting adjacent finished types. Such preparation, as the present invention is

ordinarily practiced, includes the removal of a section of the blank at a point determined by the proper location of the immediately contiguous character fields. The necessary 5 elements, therefore, for making a line of types, and such as the present invention is adapted to produce, will include means for severing and removing material from the blank, which means will preferably be in 10 the form of a slot-forming reducing-tool for transversely slotting or recessing the face of the blank, although reducing means of some other character may be employed; character-forming means, such as a suitable character- 15 forming tool, die, or impressor for forming a type-character in the face of the blank, means for actuating these devices into and out of engagement with the typebar-blank, means for sustaining a typebar-blank; and 20 means for feeding ordinarily the same longitudinally step by step towards and past the character-forming point of the machine. Ordinarily and in addition to these operating means I also find it advantageous to 25 include with the character-impressor or type-shaping devices one or more tools for facing corresponding portions of an upper edge or edges of a portion of the type-bar blank to which a die is to be applied to further trim 30 such portion and cause its shape and size to approximate more or less closely to the corresponding characteristics of the type-block which is to be formed from such portion in order that the major part of the surplus 35 and necessary material may be removed and the satisfactory action of the respective die facilitated. Shaving tools may also be used in certain circumstances adapted, respectively, for cleaning or shaving the face of 40 the portion before the formation of a type-character therein and for shaving the face of such type-character after it has been impressed or otherwise suitably shaped from the material of the blank. I also prefer to 45 include, in connection with the before-mentioned instrumentalities, a pair of cutters so disposed that they will trim the sides of the finished type and remove the surplus metal forced out by the action of the character-forming dies, and thereby bring the 50 sides of the type within the planes of the sides of the body of the typebar. In certain classes of work, these shaving and trimming tools may, however, be omitted; and it 55 is also obvious that facing tools other than those shown, and operating in various ways, may be employed, if deemed necessary.

It will be apparent from the foregoing 60 that I preferably employ, in making an integral line of types in connection with satisfactory blank-sustaining or supporting means, a plurality of tools or instrumentalities for conjointly making a character.

In applying each die or like instrumental- 65 ity to its proper section of the blank, or vice

versa, I contemplate, according to one feature of the present invention, that the mode of application shall be such as to effect a rolling of the material of the blank cross-wise of the typebar-blank, and thus removing 70 the metal away from an adjacent finished type. The rolling action to which such material is subjected will not only facilitate the reduction thereof to the contour of the die, but when the direction of such 75 rolling is as specified the flowage induced is naturally towards the sides or side of the blank, with a minimum amount of flowage lengthwise thereof; and hence the greater portion of the flowage is in a direction least 80 calculated to interfere with a finished type.

In a complete operative machine, designed to produce type after type in close succession, in the above described manner, the various instrumentalities concerned in 85 preparing, impressing and otherwise treating the material of the blank will be ordinarily conveyed to the type or character-making point of the machine. In fact, they may be conveyed periodically past that 90 point; and as such periodic movement of the parts, as well as an effective and rapid rolling movement of the die, etc., with necessarily attendant heating effect may readily be effected by mounting these various elements upon a rotary member, in the preferred form of mechanism all of the several type-shaping devices, or tools, necessary for carrying my inventions into effect are advantageously embodied in a type-forming 95 turret-mechanism, which includes, as its essential features, a rotary carrier or turret, such, for instance, as that indicated by T in the drawings—although I desire it to be distinctly understood that any suitable movable member may be employed for the purposes set forth as is also within the field of my invention—and a plurality of type-shaping tools, of which each tool is either operative for trimming a portion of the edge of 100 the blank or for removing a transverse portion of such edge or for forming a characteristic device, or type-character, in the edge of the blank, when in operative relation with such blank, or else said tools are organized for operation in groups, each of the tools of a group operating in succession to perform the various operations incident to the making of a finished type or character.

The carrier or turret is shown in the drawings as having a shaft 5, which constitutes the main driving-shaft of the machine, and is illustrated as journaled in the alined bearings 3' and 4' of the main and end frames 3 and 4, respectively. The several devices 125 which are illustrated in the present case as carried by the rotary turret and forming parts of the type-forming mechanism are: a slot-forming reducing-tool, for transversely slotting the face of the typebar-blank, two 130

sets of revoluble side-cutting-tools, the tools of which sets are adapted, respectively, to face opposite, upper edges of successive portions of the typebar blank and thereby form portions having the areas of their faces less than the areas of their respective bases, a cleaning or shaving tool for removing burs and cleaning or shaving the faces of the successive portions, after the operation of 5 the respective cutting tools thereon, a set of revoluble character-impressors, or dies, adapted, respectively, to form corresponding characters in the edge of the blank, subsequent to the operation of the cleaning or 10 shaving tool, and a finishing-tool for shaving the faces of the respective type-characters. I do not contemplate, however, that it will be necessary under all circumstances to use all of these various tools in every instance; as, for example, the cross-slotted 15 may be omitted in some cases, and the die merely rolled across the edge of the trimmed or untrimmed portion of the blank, as more fully set forth in my companion application 20 hereinbefore referred to.

For the purpose of carrying certain of these instrumentalities, the turret T is illustrated herein as having three tool-carrying shafts, designated, respectively, by 6, 7 and 30 8, these shafts being mounted in corresponding journals, which, in the present case, extend completely through the turret and are in parallelism with one another. Each of the shafts 6, 7 and 8 has fixedly secured thereto a pinion, these pinions being designated herein by 6', 7' and 8', respectively, and being also of equal size. As a means for actuating these pinions and their respective 35 shafts with equal speeds, a large spur-gear 9, 40 is loosely mounted upon an eccentrically-disposed stud 10, which is carried in fixed relation with the rotary turret and the main driving-shaft, and this spur-gear meshes with all of said pinions so that the pinions will 45 rotate in unison.

At the ends of the respective shafts 6, 7 and 8, which are located opposite the driving pinions therefor, that is, at the left-hand ends of said shafts, certain of the aforesaid devices are shown in the drawings as 50 mounted for operation by such shafts. The tools carried by the shaft 6 are preferably in the nature of cutters, and are so shown, see r, (although metal removing or reducing tools 55 of other kinds may be employed,) and these cutters are shown herein as separate members carried in channels radiating from the center of a tool-head 12, which is also fixedly secured to the shaft 6; and these cutters are 60 capable of radial adjustment in the channels of the tool-head, for the purpose of regulating the cut to be made by the respective tools, when brought into operative relation with the typebar-blank. In the present case the

cutters are shown as held securely in position, after adjustment, by means of clamp-screws 12', although it is obvious that any other desired holding means might be employed. The rear walls of the channels in which the cutters r are seated are shown at 70 12" in Fig. 14.

The shaft 7 is shown in the drawings as carrying a series of cutters s, and corresponding in number and circumferential position with the respective cutters r, carried by the 75 shaft 6, so that, when any one of the cutters r is brought into operative relation with the typebar-blank, the corresponding cutter s will also subsequently operate upon said blank. The cutters r and s, as well as the 80 character impressors, or dies, carried by the shaft 8, are shown in the present case as mounted for revolution in the same plane, and they are so organized with relation to each other that, when the typebar-blank is 85 held stationary, the respective associated cutters and die will for each die operate upon the same portion of the typebar-blank. The cutters s are also held in place, in this instance, in the same manner as the cutters r, 90 that is, by means of clamp-screws 13' engaging the cutters seated in channels in a tool-head 13.

The character-forming impressors, or dies, 95 may be either fixedly secured to, or formed integral with, a die-carrier, such as 14, and the respective dies also correspond in number and circumferential position with the corresponding cutters r and s, each of these dies, which are designated herein by t, having a characteristic device in intaglio or indentation, so that, when brought into operative 100 relation with the blank, such die will form the corresponding character in cameo, or relief, in the face thereof.

For the purpose of maintaining the tools against movement transversely of their plane of revolution, the tool-carrying heads 12, 13 and 14, and the corresponding pinions 6', 7' and 8', are in close bearing engagement with 110 the respective ends of the turret adjacent to the long journals therein carrying the tool-shafts, and, hence, a very accurate positioning of these tools is obtained relatively to the turret and longitudinally of the axis of 115 rotation thereof. It will be understood that suitable provision should be made for preventing any longitudinal movement of the turret itself. In the present case the stud 10, (see Fig. 5) is in bearing engagement with 120 the inner end of the journal-bearing 3', while a collar 5' is illustrated as carried upon the main driving-shaft and filling the space between the left-hand end of the turret and the inner end of the journal-bearing 4'.

A portion of the periphery of each of the tool-carriers 12, 13 and 14 is left blank, in order that said carriers may clear the type-

bar-blank when the shafts 6, 7 and 8 are not rotating in their journals, the various tools being then inoperative.

The slot-forming reducing-tool which I prefer to use is illustrated herein as a saw at *u*, having its cutting edge substantially concentric with the axis of the turret when the saw is in its inoperative position, (although other means suitable for the purpose may be employed,) and this tool is also shown as having a pivotal connection with the turret by means of a shaft, such as 15, (see Fig. 2) mounted for oscillation in a long journal-bearing in the turret, the slot-forming tool being in fixed connection with said shaft. For the purpose of preventing longitudinal movement of said shaft, and, hence, of the saw, the turret is illustrated as having a pair of bearing-faces, formed by a bifurcation or recess 16, and these bearing-faces are adapted to be engaged by a collar 15', which is shown as keyed to the shaft 15 for rotation therewith. The saw used, is preferably separate from its carrier and removably connected therewith, as shown in Figs. 13 and 14, in which the carrier designated by 17 is illustrated, forming part of the shaft 15, (although it may be a separate piece, detachably secured thereto,) and as having a movable jaw 17', adapted for holding the saw *u* against the fixed jaw 17'', set-screws 18 being shown for holding the movable jaw and the tool in fixed engagement with the fixed jaw and the body of the carrier. The slot-forming reducing-tool *u* is, in the present case, normally held out of operative relation with the typebar-blank, and, as a means for holding the tool in this position, a brake-bar 19, carrying, at the end thereof located, adjacent to the free end of the saw, a brake-shoe 19', is shown as fixedly secured to the carrier 17 and as spring-held, so as normally to maintain the brake-shoe in engagement with a peripheral cam-face reduced portion 6'' of an actuator or cam, carried by the tool-carrying shaft to which the cutters *r* are secured. In the present instance, the brake-shoe is represented as held against said cam-face by means of a spiral spring 20, pressing against the inner end of the brake-arm and coiled around a stud 21, in fixed relation with the turret, the free end of which stud extends through an aperture in the inner end of said brake-arm. It is intended that the spring 20, which is a compression spring, will exert a force sufficient normally to hold the shoe 19' against the reduced portion or cam face 6'' and also that when the shaft 6 is rotated the shoe will be carried off from the said cam face and up on to a portion of the cam of greater radius, thereby causing the free end of the saw to be carried outward with relation to its normal path of movement and into a position for transversely slotting the typebar-blank.

From the foregoing description of the operative connections for the slot-forming tool, or saw, the side-cutting tools and the character-impresors, or dies, it will be apparent that, on the operative actuation of any one of the shafts 6, 7 and 8, all of these tools will be brought into operative position, and actuated to form a type-blank having a character formed therein, it being understood, of course, that the main driving-shaft and consequently the turret are continuously rotated, as, for instance, by means of the band-wheel 22.

For the purpose of selectively bringing any tool of each series into position for operating upon the typebar-blank, I make use of starting means, a form of which will now be described. Each of the tool-carriers, 12, 13 and 14 is provided, as hereinbefore described, with a series of members, or tools, corresponding in number and position with the respective members, or tools, of the other tool-carriers, and in the organization of mechanism illustrated an impression, or character is formed as the result of the conjoint action of a corresponding tool on each of these carriers although as before stated, and as more fully explained in my companion application, this employment of the entire series of steps or operations will not generally and in every case be necessary. The machine shown in the drawings is illustrated as having twelve tools, or members, on each carrier, and the corresponding members, or tools one in each series, are shown in the drawings as controlled by a common, character-indicating key on a suitable key-board, which, in this instance, is furnished with twelve keys, adapted for selectively bringing into operative position that set of coöperative members, or tools, which is controlled by such key and its connected devices. It is, however, of course to be understood that a complete machine is to be equipped with a full set of keys and character-forming tools.

The key-board of the machine is illustrated in Figs. 1 and 2, and, as before stated, is furnished with a plurality of keys, each of which is designated in a general way by *K*, these keys being shown, in the present case, as secured to corresponding key-levers 23, pivoted at their rear ends to the base of the machine in any well-known manner, as, for instance, by being hung on the rods 24, each of said keys and key-levers being also shown as returned to its normal position, after actuation, by means of respective springs 25, as is customary. Each of the key-levers is represented as having pivotally secured thereto a connecting-rod or latch-actuating rod 26, preferably in the form of a flat-spring having an upper bent or hooked end, adapted to engage and release a corresponding latch guide-pin or stud 27 one for each

actuator, and each having a channel in its inner side, is provided for holding the upper end of the latch-actuators in working position.

5 The latches, which are controlled by the latch-actuating rods, and designated by 28, are disposed in an arc of a circle concentric with the axis of the turret; being carried by a frame 29, which may be formed integral 10 with the main frame 3, or it may be detachably and fixedly secured thereto. This latch-carrying frame is preferably provided with two end-pieces 29' and 29'', having registering slide-ways radially disposed relatively 15 to the axis of the turret, and in which slide-ways the latches 28 are shown as carried for reciprocation into and out of operative relation with the turret-mechanism. (See Figs. 26 to 29.) The end-pieces 29' and 29'' 20 serve as stops for limiting the movements of the latches in each direction. Each of the latches is illustrated as having a pin-stop 28', for engaging the frame-piece 29', to limit the forward movement of the latch, and 25 is also provided with a reduced portion, adjacent to its rear end, to form a stop-shoulder 28'', for holding the latch in its normal retracted position, by engagement of such stop-shoulder against the corresponding stop-face 30 formed by the rear wall of the slide-way in the end-piece 29'' of the latch-frame. The slide-ways in this end-piece 29'' are shown as of considerable height, so that not only may each latch have a free, longitudinal 35 movement in its respective way but it is also capable at its rear end of having a slight swinging movement therein. The rear end of each latch is also normally sustained in the retracted position of the latter by means 40 of a light spring one for each latch—such, for example, as designated by 30—to maintain the stop-shoulder 28'' in locked engagement with the cooperative shoulder of the end-piece 29'' of the latch-frame. A 45 stronger spring, of helical form, is designated by 31, for actuating the latch to project the same into the path of the turret-mechanism, when the force of the spring 30 is overcome by the pull of the hooked end of 50 the actuated latch-actuating rod 26. It will be obvious that, when the latch is restored to its original, retracted position, the spring 30 will cause the locking of the stop-shoulder 28'' with the end-piece 29'' of the latch-frame.

55 As a means for bringing the turret-mechanism into operative relation with a latch which has been actuated by the depression of its corresponding key, the shaft 8 is shown 60 herein as having fixedly secured thereto a starting-arm—such, for instance, as that designated by *w*, (see Figs. 13, 14 and 26)—which starting-arm is illustrated as formed with a clip 32, adapted to be clamped to the

shaft 8 in any desired position. This starting-arm is shown as having a starting-finger *w'*, in position to be engaged by the inner end of a projected latch, and as also having a latch-replacing finger *w''*, for restoring the latch to its original position during 70 its actuation thereby.

75 It will be understood from the preceding description of the turret-mechanism, and by reference to Figs. 11 and 14, that the actuation of the starting-arm *w* serves to rotate the shafts 6 and 7 and the tools carried thereby, but, as this action only takes place during the short interval of time in which the starting-arm is in engagement with the latch, it is evident that some other 80 means must be employed to continue the actuation of the tool-shafts after the starting-arm has passed the latch. I prefer to utilize the initial rotation, imparted to these tool-shafts by the latch and the starting-arm, as the means for continuing the actuation of the turret-operated devices, until the operation of forming in the blank an impression or character, corresponding to the key depressed, has been effected. In Figs. 90 85 to 23, inclusive, I have illustrated in detail one means for continuing this initial rotation of each of the tool-carrying shafts. (See also Fig. 14.) In these views the shaft 6 is shown as having a shiftable spur-gear 95 33, mounted thereon and held against rotation relatively to the pinion 6'. In the present case the spur-gear 33 is illustrated as held against rotative movement, relatively to this pinion, by means of guide-pins 34, 100 screw-threaded into said spur-wheel and adapted to slide through transverse apertures in the body of the pinion 6'. This spur-wheel 33 is also shown as having fixedly secured thereto a hub or barrel 35, 105 which is herein represented as having longitudinal bores, through which the guide-pins 34 pass, the pins and the bores being, respectively, of two diameters, in order to form 110 stop-shoulders for maintaining the spur-gear, the hub and the pins in rigid connection. To further increase the solidity of the construction the hub 35 also preferably slides on the hub of the pinion 6', as shown 115 in Figs. 22 and 24.

120 As a means for bringing the spur-gear 33 into, and carrying it out from, engagement with the driving internal gear, which is concentric with the axis of the turret-mechanism and will be hereinafter described, the hub 35 is shown as having a pair of cams, designated, respectively, by 36 and 37, the former of which has its cam-face inclined in one direction and is adapted for coupling 125 said spur-gear with the driving internal gear, and the latter of which has its cam-face inclined in the opposite direction and is so disposed as to release the spur-gear

from the driving internal gear after the operation of forming an impression or character has been completed.

The main-frame 3 of the machine is illustrated in the present case as constituting a gear-carrier, adapted for carrying the main driving internal gear and two other internal gears concentric with the main internal gear.

The driving internal gear 38 is shown herein as mounted in the gear-carrier and as suitably held against movement relatively thereto, this internal gear being concentric with the axis of the turret and so located that, when the spur-gear 33 is slid to its extreme position to the right, the teeth of this gear will mesh with those of the internal gear. For the purpose of permitting these two gears 33 and 38 to be brought into mesh with a minimum liability to improperly catch against each other, the teeth of the spur-gear are illustrated in Fig. 25 as beveled for a considerable peripheral distance, on that face of the spur-gear which is adjacent to the internal gear, while the teeth of the driving internal-gear are shown as similarly beveled for a considerable distance on that side of said internal gear which is adjacent to said spur-gear. (See Figs. 11, 21 and 23.)

It will be apparent that some suitable resistance face must be opposed to the action of each of the cams 36 and 37, in order that the operations of coupling and uncoupling the spur-gear 33 and the internal gear 38 may be properly effected. These resistance faces are shown in the drawings as oppositely-inclined cam-faces 39' and 40', formed by oppositely beveling the inner faces of a pair of segments, such as 39 and 40, which are illustrated as located in parallelism with each other and in fixed relation with the gear-carrier or main-frame 3. These cam-segments may be separated from the gear-carrier and secured thereto in any suitable manner, as by means of set-screws. (See Figs. 21 and 23.)

In the normal operation of the turret-mechanism, the cams 36 and 37 are so disposed that each will be carried in an orbit by the turret and in inoperative relation with its respective co-operative cam-face 39' or 40'. The coupling of the spur-gear 33 with the internal-gear 38 is dependent upon the fact that, when the starting-arm *w* is engaged by a latch, the rotation of the shaft 6, resulting therefrom, causes the cams 36 and 37 to rotate with said shaft 6, relatively to the turret, and thereupon, when the cam 36 comes opposite to the cam-face 39', said cam will be forced up said cam-face, and hence the gear 33 will be slid along the shaft 6 into mesh with the internal gear 38. (See Fig. 24.) After the turret has nearly completed a rotation about the main driving-shaft 5, the cam 37, when it comes opposite the cam-face

40', is carried outward, up said cam-face, in a lateral direction opposite to the direction of movement just described with reference to the cam 36, and the spur-gear 33 is uncoupled from the main internal-gear 38, 70 (see Fig. 22.) The two cams 36 and 37 are returned to their normal positions preferably by the striking of the cam 37 against the abutting end of the cam-segment 39, this abutment designated by 39'', being shown as 75 in position for engaging and turning the cam 37 after said cam has been carried to its normal position to the left, as seen in Fig. 22. This striking of the abutment 39'' by the cam 37 serves, on the turning of said 80 cam, to bring the same to its normal position, and the cam-face 6'' is so disposed that the brake-shoe 19' is simultaneously brought into engagement with said cam-face (see Fig. 13) to restore the slotting-tool, the side-cutting tools, the impressors, or character-forming dies, and the starting-arm *w*, to their normal positions.

It will be evident from the preceding description that I employ a plurality of series 90 of shaping and type-making tools, in the preferred form of my invention, the tools of each series corresponding, respectively, in number and position with the respective tools of the other series, together with starting means adapted for selectively bringing a corresponding tool of each of these series into such a position that, when operated by its actuating means, these tools will be carried in a predetermined order into engagement with a portion of the edge of a typebar-blank, the tools of each series being in the present case movable separately from those of the other series and rotative in unison therewith. The tools of each series are 100 also shown as movable in a plane common to the tools of the other series. Moreover, it will be apparent that I make use of a plurality of corresponding, separately-movable, shaping and type-making tools, and means 110 for actuating the tools in cycloidal paths, preferably of trochoidal character, into and out of engagement with a portion of the edge of a typebar-blank. It will also be obvious that I have illustrated one pair of 115 such tools, viz., the side-cutting tools, as successively movable in prolate and curtate epitrochoidal paths, preferably of a hypotrochoidal character.

The operation of the cutting-tools carried 120 by the shaft 6 is illustrated in diagram in Fig. 30. In this view the typebar-blank is shown at B, and the side-cutting tool *r* is illustrated as rotating with the axis of the shaft 6 while revolving around the shaft 5. 125 The cutting edge of this tool lies within the pitch-circle of the spur-gear 33, and, hence, the line traced by the edge of the cutter is a curtate hypotrochoid having its terminus just outside the face of the typebar-blank 130

and below the upper edge thereof, so that, when the cutter is moving in the direction indicated in this view, it will cut diagonally downward and outward, through the face 5 of the blank, and face the edge thereof at the right-hand side, as seen in said figure, thereby permitting a progressive, forward movement of the tool into and out of engagement with the blank. This progressive advance 10 of the cutter *r* assures a continuous, advancing movement thereof during the period when the cutter is describing the last portion of one hypotrochoidal path and the first portion of the next succeeding path, 15 and this causes a perfectly smooth and even cutting action for facing the edge of the blank.

Fig. 31 illustrates, also in diagram, the operation of one of the cutters *s* for facing 20 the side of the blank opposite that operated upon by the cutters *r*. In this view a cutter *s* is illustrated as rotating with its shaft 7, while revolving around the axis of the main driving-shaft 5, but, in this case, the cutting 25 edge of the tool is shown as extending outside of the pitch-circle of its driving spur-gear. Hence, in order to bring the cutter *s* into proper relation with the typebar-blank, it is obvious that a driving spur-gear for 30 this cutter should mesh with an internal gear of smaller diameter than the diameter of the internal-gear 38, with which the spur-gear 33 meshes. A spur-gear and internal-gear adapted for actuating the cutter *s* are 35 designated, respectively, by 41 and 42, and will be hereinafter more particularly referred to. As the cutter *s* is adapted for cutting the left-hand side of the blank B, as seen in Fig. 31, it will be apparent that provision must be made for removing, or facing, 40 the edge of the blank while the tool is advancing in a direction toward and across the blank. By locating the cutting edge of this tool beyond the pitch-circle of the spur-gear, the edge of the cutter is caused to travel 45 in a prolate hypotrochoidal path, and engages the face of the blank by a movement in a direction as indicated by the loop portion of its path in Fig. 31, said cutter passing down into the blank and out at the side thereof in a direction inclined oppositely to 50 that in which the opposite edge of the blank is faced by the cutter *r*, as described with reference to Fig. 30. Moreover, the movement of this cutter *s* to the rear, after it has 55 faced the blank, is continued sufficiently far to permit it to be carried a considerable distance away from the blank, so that the cutter will not interfere with the blank when 60 said cutter commences to move toward the apex of the succeeding branch of the curve. A loop of considerable width and length is 65 thus formed, beyond the node of intersection of the hypotrochoidal branches.

65 The two species of curves, defining the

movements of the edges of the cutters *r* and *s*, are of great practical importance in the operation of type-forming turret-mechanism, such as that described herein, as, by the actuation of the respective cutting-tools in 70 curvate and prolate hypotrochoidal paths into and out of engagement with the typebar-blank, I am enabled to face both the front and rear, upper edges of the blank, and to carry the tools away from the blank 75 as soon as they have faced those edges, and thus preclude the possibility of interference of the tools with any portion of the blank. In addition to this I also obtain the important advantage of operating the tools by 80 continuous, progressive movements, or rotations, of their respective carriers or shafts. I, therefore, consider the actuations of a shaping tool in a trochoidal path as an important feature of my invention. 85

In Fig. 32 the operation of the character-impresser or die is illustrated in diagram, and, in order to secure a perfect impression, and thereby form a character having a plane face perpendicular to the vertical axis of the 90 blank, the die should move in pure hypocycloidal paths having cusps at the termini of the respective branches of the curve. Each of the dies *t*, is therefore, shown as movable in such paths; and it will be observed that 95 the spur-gear shown herein as adapted for actuating the die has its pitch-circle in such a position that the gear may be driven by an internal gear intermediate of the gears 38 and 42. A spur-gear and an internal gear, 100 suitable for actuating the dies, are designated herein by 43 and 44, respectively, and will be hereinafter more particularly referred to.

It will be noticed that the tools carried by the shafts 6, 7 and 8 are so disposed that 105 corresponding tools carried by different shafts operate, with respect to one another, at distances apart corresponding to one rotation of each of the shafts, that is to say, a tool carried by the shaft 6 is disposed so as 110 to pass a given point at such a distance in advance of the passage of the same point by the co-operating tool of the shaft 7 as corresponds to one rotation of each of said shafts; while the tool carried by the shaft 115 7 passes the same point one rotation in advance of the corresponding impressor, or die, carried by the shaft 8. This will be apparent by reference to Figs. 30 to 32, inclusive, in which the cutter *r* is illustrated 120 as beginning its movement one rotation in advance of the tool *s*, while the cutter *s* begins to move one rotation in advance of the die *t*. As the tools carried by these several shafts are illustrated as movable into and 125 out of engagement with the face of the typebar-blank, it will be evident that the tools are actuated in epicycloidal paths subtending similar, and, in the present case, concentric, orbital arcs, and that those epi- 130

cycloidal paths located adjacent to the blank have their termini in a common locus in said blank, this locus being the type-formative portion of the typebar-blank.

5 In order to obtain satisfactory commercial results in the manufacture of type-characters or other impressions in a solid blank, it is desirable that this blank shall be of a relatively-ductile metal, preferably a 10 type-metal of suitable composition, since, if the blank opposes any great resistance to the action of the side-cutting tools and the dies, these tools and dies would soon become so worn that the formation of sharp, clean-cut 15 type-characters, in proper alinement, would be rendered impracticable. In addition to this, an important feature of the invention resides in so shaping one or more of the upper edges of a portion of a typebar-blank to 20 be impressed as to reduce the area of the face of such portion relatively to the area of the base thereof, and, preferably, these edges are so trimmed that such face is formed of relatively - small area, as compared 25 with the area of such face after the impression of a character therein by the corresponding impressor or character-forming die. As the tools carried by the 30 respective shafts are revolved successively into and out of engagement with the typebar-blank, and preferably in a common plane, the operation of each tool of a set of coacting members is performed and completed before the next tool of such series 35 begins to shape the blank, thus making each operation upon the blank entirely separate from, and independent of, every other one, and rendering interference impossible.

From the description of the turret-mechanism it will be seen that my invention 40 contemplates the provision of means for periodically conveying past suitable blank - sustaining means and in inoperative relation with a proper blank therein a tool operative 45 for shaping a portion of the face of such blank, and that this tool is only carried intermittently into operative relation and engagement with the blank. In the present case this tool is illustrated as brought into 50 operative relation with the blank by enlarging the orbital path of the tool, this being the case both with the slot-forming or blank-recessing saw and with the revolute cutters and dies.

55 The internal gear 38 has been hereinbefore described as constituting the main, driving, internal gear, and as operative for revolving the spur-gear 33 for rotating the shaft 6, and thereby actuating all of the 60 type-shaping tools that are movable relatively to the turret. This gear is concentric with the axis of the turret, but, while it forms a suitable driving-gear for the turret-mechanism, it does not alone constitute the 65 only means existing in the present illus-

trated machine for effectively locking the respective, revoluble tools against slipping, during the time when they are shaping a portion of the edge of the blank. Moreover, each of the shafts 6, 7 and 8 must have 70 its axis at a different distance from the axis of the main driving-shaft 5, for the purpose of carrying the respective cutters and dies in the proper hypocycloidal paths described with reference to Figs. 30, 31 and 32. 75

The internal gear 44, before referred to, is illustrated (see Figs. 7 and 11,) as a segmental gear forming part of a ring mounted in the gear-carrier 3; and the third internal gear 42, also before referred to, is represented as of similar segmental construction and as also mounted in said gear-carrier. The gears 42 and 44 are shown in the drawings as disposed in parallel planes, with their pitch-arcs concentric with the axis of 85 the turret. Means are also illustrated for adjusting each internal gear about the axis of the turret, relatively to the gear-carrier, and for holding an adjusted gear in its adjusted position, so as to bring the gear into 90 proper mesh with its corresponding spur-gear at the proper period.

The means illustrated in the present case for adjusting the positions of the internal gears are best shown in Figs. 3 and 4. Each 95 of the internal gears or rings is illustrated as having a shoulder 45, formed by removing peripheral portions of the annuli in which the teeth are formed and against which impinge oppositely - disposed stop-rods, or pins, 46 and 47, respectively, the outer ends of these pins being adapted to enter alined bores, such as 48 and 49, in the gear-carrier 3. Adjusting-screws 50 and 51 are illustrated as working in these bores, so 100 that, by properly manipulating said adjusting-screws, the internal gears may be independently adjusted slightly to permit their teeth to be brought into proper mesh with the corresponding teeth of their respective 110 spur-gears.

As a means for locking the respective tools against slipping, while they are operating upon the typebar-blank, each of the internal gears is preferably formed with a gear-segment, radially adjustable relatively to the axis of the turret, together with means for effecting such radial adjustment, relatively to the spur-gear corresponding to such internal gear, and for holding the segment in 120 position. These segments 38', 42' and 44', respectively, are preferably hardened steel, or similar, members secured in vertical guideways formed by removing a portion of the rear, vertical face of each of the mentioned annuli, adjusting-screws 52 being illustrated, for raising these gear segments, to bring them into close mesh with their respective spur-gears, so that slipping, or "back-lash", will be prevented. These seg- 130

ments are also illustrated as alined with the longitudinal axis of the typebar-blank, so that the locking of the tools against slipping will be effected at the proper moment.

5 The term "gear", "gearing", etc., as used herein, include both the toothed and frictional varieties in the same manner as these terms are employed in Patent No. 399,746, granted to D. W. Dodson and F. H. Rich-
10 ards, March 19, 1889.

Each of the tool-carrying shafts is illustrated (see Fig. 14) as extended for a considerable distance beyond the turret, toward the right-hand end of the machine, this pro-
15 longation being provided in each instance for the purpose of carrying the respective spur-gears, such as 33, 41, or 43, each of which meshes with the corresponding one of the internal gears previously described. The
20 spur-gear 33 is provided with teeth throughout its entire periphery, and is shiftable longitudinally of its shaft, while held against rotation relatively thereto, as hereinbefore specified: the gears 41 and 43, however, are
25 shown as fixedly secured to their respective shafts 7 and 8, and as having teeth around portions only of their peripheries, that portion of the periphery of each of these spur-gears which comes opposite its respective, in-
30 ternal gear, when the shafts are held in their normal positions against rotation relatively to the turret, being blank, so that neither of the gears 41 and 43, can at such time mesh with the teeth of the corresponding internal
35 gears 42 and 44. The dotted lines in Fig. 14 mark the limits of the parallel planes in which these spur-gears are illustrated as adapted to rotate, these planes, of course, corresponding with the planes of the respective, coöperative, internal gears.

40 Any suitable means may be employed for holding the typebar-blank B in position to be operated upon by the tools of the turret-mechanism dependent upon the particular character of the blank employed. In the present case this blank is illustrated as a comparatively short-length blank, is conveniently held or supported in a blank-carrier, which is designated in a general way by C, and in the illustrated construction is in the nature of a slide-block, movable transversely with respect to the plane in which the tools are carried by the turret, in suitable ways, for the purpose of enabling the successive portions of a contained blank to be brought in proper relation to the turret mechanism, and having an adjustable jaw to permit the engagement or release of the blank. The main jaw 53' of the slide block and the auxiliary or movable jaw 54 of the carrier are adapted for firmly holding the blank, suitable clamp-screws 55 being shown as passing through a projection 53'' of the slide block for engaging such movable jaw and releasing the same; although, as is ob-

vious, any suitable form of clamp-actuator may be employed. The ways 56 which control the direction of movement of the blank-carrier are illustrated, as suitable guides bolted to the base of the machine. In the present case, the blank-carrier is represented as adapted to be fed by a screw-motion, the feed-screw 57 which is operative for advancing such blank-carrier being illustrated as working in a longitudinal bore of the carrier, and as having its right-hand end supported by a long journal-bearing in that portion of the main-frame 3 which is contiguous to the base 2 of the machine. For the purpose of preventing slipping of the feed-screw in a longitudinal direction, the shaft thereof is illustrated, as having a reduced portion 57' adapted to be embraced by a keeper-plate 58, suitably secured to the inner side of the standard 3 (see Figs. 5 and 7.) The blank-carrier, or slide-block, is also shown (see Fig. 8) as having a spring-pressed locking pin 59, the inner end, 59', of which is shaped to serve as a nut to engage in the helical groove of the feed-screw. When it is desired to move the slide-block a considerable distance along the feed-screw, it is obvious that the locking-pin should first be retracted and drawn out of engagement with said groove.

At its right-hand end the shaft of the feed-screw 57 is illustrated as having fixedly secured thereto a gear-wheel 60, the hub of which has a firm bearing against the outer face of the main-frame 3. The teeth of this gear-wheel are in mesh with the teeth of an idle-wheel, 61, which is shown as carried by a stud 62, likewise secured to said frame, the teeth of this latter wheel being also shown as in mesh with the teeth of a third gear-wheel 63, rotatably mounted on another stud 64, fixed to the frame 3. This gear-wheel 63 is represented herein as having a long sleeve, or thimble, 63', to which is fixedly secured, at a proper distance from the outer end of the spur-gear, a ratchet-wheel 65, suitable means, such as a collar 66, being shown for holding the ratchet-wheel in position longitudinally of the stud. An oscillatory pawl-carrier 67, is illustrated, as also mounted on the sleeve 63', and as filling the space between the ratchet-wheel and the spur-gear, a pawl 68 being shown, as pivoted on this carrier, in operative relation with the teeth of the ratchet-wheel, and as having a suitable spring, such as 69, for maintaining the pawl in engagement with the ratchet-teeth.

As a means for actuating the pawl 68, a connecting-rod 70, is illustrated as having a pivotal connection with the pawl-carrier 67, and as having, at its opposite end, a similar pivotal connection with the free end of a rock-arm 71, fixedly secured to a rock-shaft 72, journaled in the upper side of the main-frame 3. This rock-shaft 72 is also repre-

sented in the present case as having fixedly secured thereto a lever 73, the main arm 73' of which controls the downward movement of a plunger 74, while the other arm 73'' is normally held up by a spring, such as 75, seated in a suitable recess at the upper part of the frame 3. The frame is shown as cut away (see Figs. 2 and 9) to permit free movement of this lever 73, and as also 10 re-
cessed at its under side for the reception of a pivoted member, or rock-arm, such as 76, which controls the upward movement of the plunger 74, and in turn has its downward or inward movement governed by such 15 plunger, the plunger being illustrated herein as guided by the walls of an opening connecting the two main cut-away portions of the main-frame just referred to. (See Fig. 9.) The downward movement of the 20 rock-arm 76 is also illustrated as limited by a suitable stop 76'.

For the purpose of indicating the length of blank to be fed for the formation of a letter, the shaft 8 is shown as carrying a 25 feed-actuator or indicator I, which, in the present case, is illustrated as a cam-wheel having a plurality of feed-members, or indicator-members, in the form of cams, such as 77, 78 and 79. In case a uniform length 30 of blank were to be fed at each operation, it is obvious that only one cam would be necessary, but, as different characters require the feeding of different lengths of the blank, I have shown herein a number of cams corre-
sponding to the number of different lengths 35 of blank required by the characters illustrated in connection with the present machine. It will be seen that only three cams are illustrated, each of these being adapted 40 to control the movement of the blank for four separate characters, the cam-face 79 being operative for feeding the blank a distance controlled by one tooth of the ratchet-wheel, while the cams 77 and 78, respec-
tively, are adapted to correspondingly actuate the blank a distance governed by two 45 or three of the ratchet-teeth, as the case may be. It will be apparent by reference to Fig. 9 that the cam 79 controls the feed for the 50 characters of least width, the cam 77 for those of medium width and the cam 78 for those of greatest width. It will also be apparent by reference to Fig. 9 that each of the cams 77, 78 and 79 is of a different radial length, and is differently located with refer-
ence to the axis of shaft 8.

As the starting-arm *w* comes into engagement with a latch, the cam-face corresponding to the die or character controlled by such 60 latch will engage the depending finger 76'' of the rock-arm 76, and will force the same outward a distance corresponding to the number of ratchet-teeth controlled by such cam-face, it being understood that each of 65 the cam-faces or feed-actuators is in a po-

sition corresponding with the position of its respective die or dies in circumferential direction about the shaft 8.

From the description of the slide-block and the turret-mechanism it will be obvious 70 that one of the features of my invention is the provision of a tool-carrier blank-sustaining means, the former of which and a blank supported in the latter are adapted to be actuated one transversely of the other, and 75 means for shifting one of these members in a direction transversely of, and preferably perpendicular to, the other, the tool-carrier being shown herein as actuated transversely of the blank-carrier, while the blank is shift- 80 able transversely of the tool. I need not employ such a blank-carrier as herein described, however, as I consider within the scope of my invention, in a machine of this type, any means for actuating a typebar- 85 blank longitudinally, while actuating the tool-carrier transversely of the blank.

Another of the important features of this invention is, as will be evident from the preceding description, a feeding-mechanism, 90 operable by the type-forming turret-mechanism, and adapted to intermittently feed a typebar-blank transversely of the plane of rotation of the turret-mechanism, for the purpose of presenting successive portions of 95 the typebar-blank to the action of the type-forming mechanism. This feeding-mechanism should be of variable-stroke, as before indicated, in order to make provision for the feeding of different lengths of the blank 100 for different characters.

The devices which I prefer to employ for actuating the typebar-blank constitute a blank-feeding mechanism, embodying an indicating mechanism having a plurality of 105 indicators controlling variable movements, respectively, of the indicating mechanism, and selectively operative with their corresponding type-shaping tools, the blank-feeding mechanism also embodying means, oper- 110 ative by the indicating mechanism, for feeding the typebar-blank a distance correspond-
ing to such indication.

The indicators, or feed-actuators, are illus- 115 trated herein as carried in fixed relation with one of the spur-gears of the turret-mechanism, and as corresponding in number and circumferential position with their respective character-forming dies, the means for selectively bringing the feed-actuators, respec- 120 tively, into operative relation with the blank-feeding mechanism being the same as hereinbefore described with reference to the revoluble type-shaping tools, viz., the starting-arm, latches and key-actuated devices. As 125 the feed-actuators or feed-cams are operative, respectively, at different radial distances from the axis of the spur-gear for the character-forming dies, the pawl-actuating means, connected with the pawl of the pawl-and- 130

ratchet-wheel mechanism, will have variable-strokes corresponding to the distances of the respective feed-actuators, or indicators, from the axis of such spur-gear.

- 5 I find it advantageous to embody in the blank-feeding mechanism means operative with the main driving-shaft and adapted to actuate the feed-member of the indicating mechanism for feeding the blank a distance 10 corresponding with the distance shown by the indicating mechanism. This actuating means is illustrated (see Fig. 10) as a stud 80, in fixed relation with the shaft 5, and in position and adapted to engage an arm 67', 15 of the pawl-carrier 67, to feed the ratchet-wheel and also restore the indicating mechanism to its normal position.

The operation of a machine embodying my invention and constructed as herein set forth 20 is as follows: When the turret-operated tools are in their normal inoperative positions, and one of the keys of the key-board is depressed, the latch corresponding thereto will be projected into the path of the starting-arm *w*, 25 as shown, for instance, in Fig. 15. It being understood that the turret is continuously rotating in the direction indicated by the arrow in said figure, it will be seen that the latch will first engage the starting-finger *w*, 30 and will thereupon rotate the shaft 8, which in turn will cause the shafts 7 and 6 to be correspondingly rotated. At the same time the free end of the slotting-tool *u* (provided the latter is used) is projected out of its 35 normal path into position to slot the type-bar-blank. The several positions assumed by the starting-arm, before it passes beyond the latch, are shown in Figs. 27 to 29, inclusive, and it will be noticed that the latch-replacing 40 finger *w'* will push back the latch, before passing the same, into a position where the spring 30 will become operative to force the rear end of the latch upward, to engage the locking shoulder thereof with the corresponding shoulder of the frame 29'.

By the partial rotation of the tool-carrying shaft 6 the cam 36 is brought to the radial position shown in Figs. 16 and 23, and, in riding up the cam-face 39' of the cam 39, 50 shifts the spur-gear 33 into engagement with the teeth of the internal-gear 38, so that the coupling of these gears will be effected before the starting-arm is released by the latch, thereby maintaining a continuous, rotative 55 movement from the moment of the commencement of the rotation of the starting-arm until the proper coupling of these two gears is assured. At the same time the proper cam-face of the indicator I comes 60 into engagement with the finger 76' of the rock-arm 76, and actuates the indicating mechanism to draw back the pawl, the actuating-stud 80 shortly thereafter forcing back the arm 67', (see Fig. 10,) to cause the rotation of the ratchet-wheel, and thus actuate

the feed-screw to move the blank-carrier a distance to the left, as seen in Fig. 5, corresponding to the space occupied by the impression or character to be formed, the indicating mechanism being simultaneously restored to its normal position. 70

Immediately after the feeding of the blank has been accomplished, that is, if the organization is such as to effect a feed before the slotting tool or saw *u* comes into 75 operation and this tool is provided on the machine, it comes into contact with the blank, as illustrated in Fig. 16, and cuts a transverse slot or kerf in the same of gradually increasing depth from the point to the heel 80 of the saw (see Figs. 16 and 17), thus setting off a type-blank segment on the type-bar-blank. The first side-cutting tool corresponding to the key depressed, that is, the tool carried by the shaft 6, then faces one 85 edge of the portion of the type-blank in the plane of the various tools by its movement in a curtate hypotrochoidal path (see Fig. 17;) and thereafter the second side-cutting tool corresponding to such key, viz., the tool carried by the shaft 7, faces the opposite edge of such portion by its movement in a prolate hypotrochoidal path. As soon as the head of the portion thus trimmed has been thus brought to a proper pyramidal 95 form a bur-removing shaving-tool, such as that designated by *x*, (see Fig. 13), comes into contact with the face of the trimmed portion and carries off any bur that may have been thrown up by the saw, and also 100 removes coating from the face of such portion which may be present, thereby preventing the clogging of the die and malformation of the type by loose pieces of metal and also exposing a smooth, bright 105 surface adapted to form a clear-cut type-character, when acted upon by the character-forming die. The cutter *x* is herein illustrated as adjustably secured to the rotary 110 turret, in such a position as to be operative 115 at all times for removing loose burs and a thin shaving or turning from the face of the section to be operated upon.

Immediately after the last-mentioned shaving operation is effected the proper impressor or character-forming die, also corresponding to the key struck, which die is carried by the shaft 8, comes into engagement with the bright surface of the blank, and, by its movement in a pure hypocycloidal path, forms in the blank a type-character, the face of which is in a plane perpendicular to the vertical axis of the blank and common to the faces of all of the other type-characters which might be formed in 120 such portion of the blank by the other dies carried by the shaft 8.

When the cam 37 reaches the cam 40, it is forced by the rotation of the shaft 6 to the radial position shown in Fig. 21, and 130

said cam 37 is carried up the cam-face 40' to shift the spur-gear 33 (see Fig. 22) and uncouple the same from the internal gear 38. When this cam 37 reaches the abutment 39" 5 of the cam 39, the cam 37 is given a slight, rotative movement, which, being communicated to the train of gearing of the turret-mechanism, restores all the parts to their normal positions and causes the brake-shoe 10 to be again brought into contact with the cam-face 6" of the shaft 6, to maintain the parts in their inoperative positions until another latch is projected into the path of the starting-arm.

15 In order to insure absolute uniformity in the positioning of the faces of the finished types, and to thereby maintain the faces of successive type-characters in a common plane, I have shown herein at y , a second 20 shaving-tool, the edge of which extends to a slightly greater distance from the axis of the shaft 5 than the tool x , and is arranged in a different plane rearward of the latter tool, see Figs. 13 and 14, thereby enabling it to cut in a greater orbit, and to shave the faces of the finished type-characters to a uniform depth, it being understood that only an extremely minute turning will be removed by this cutter. The positioning 25 of this shaving-tool circumferentially of the turret and with relation to the other tools, is practically immaterial, as the turret will, in practice, always carry this shaving-cutter over the face of the last-formed character 30 before the rotation of the turret-mechanism is stopped. In the present instance the cutters x and y are shown as adjustably mounted adjacent to each other upon a projecting carrier secured to the turret.

35 40 By reason of the disposition of the axes of the respective shafts 6, 7 and 8 at different distances from the axis of the shaft 5, (see Fig. 13,) it will be apparent that the respective spur-gears 33, 41 and 43 will 45 travel in orbits of different diameters, and these spur-gears will successively come into alignment with the typebar-blank just prior to the action upon such blank of the tool controlled by such gear, each of such gears 50 being brought into close, meshing engagement with the teeth of its respective gear-segment 38', 42' or 44', thus locking the type-shaping tool corresponding to such spur-gear against slipping in circumferential 55 direction while operating upon the typebar-blank.

In order to bring each of the finished types to a thickness corresponding to that of the body of the typebar-blank, and therefore 60 by permit the proper assembling of a number of finished typebars in a form, I have shown herein, at z and z' , respectively, a pair of cutters suitably mounted, as, for instance, upon the cross-bar 4" of the end-frame 4, and in position and adapted for

trimming the longitudinal sides of the finished type, to remove surplus metal forced sidewise by the action of the character-forming die. (See Figs. 1, 40, and 42.)

The action of the several tools for operating upon the typebar-blank to form a typebar is illustrated in detail in Figs. 33 to 42, inclusive. Each of the bars is preferably formed with a shoulder or inclined face, such as 90, by removing a portion of the 70 end of the typebar-blank, it being understood that this shoulder is duplicated at the other end of the blank, (not shown in said detail views,) by similarly removing the opposite end portion. This provides the necessary support, or backing, for the terminal characters of the bar, and also forms a means for spacing such characters at the proper distance from the usual column-separating rules. The blank being fed a distance corresponding to the length of the face of the type to be formed, the slot-forming reducing-tool or saw is brought into operation to form the reduced portion or slot 91. The first side-cutting tool r is then brought into 75 operation to remove or face the upper edge of the proper section of the typebar-blank, the direction and depth of the cut being such as to form an inclined face 92, intersecting the plain side of the blank at a 80 point some distance above the bottom wall of the slot 91. The other side of the blank is then faced in the opposite direction by the cutter s , to form an inclined side 93, sloping in a direction opposite to that of the 85 face 92. It will be obvious now, by reference to Fig. 35, that the trimmed section of the blank is of pyramidal or frusto-pyramidal form, the face being of considerably less area than the area of the base thereof. The 90 face of the blank is next traversed by the shaving-tool x , for the purpose of removing any bur which may have been thrown up by the slotting saw, and also for removing a thin shaving or coating of oxid, with 95 which the surfaces of type-formative blanks, having as their main constituent lead, are usually incrusted. After the bur is thus removed and the bright surface of the metal of the blank exposed, the die t is brought 100 into action and compresses the upper portion or face of the pyramid, or frusto-pyramid, shaped by the action of the previously-operative tools, thereby forming a type-character corresponding to the die employed. 105 This type-character 94 is shown, as having its face, or impression surface, considerably below the original upper surface of the similar surface of the remaining portion of the type-blank and the section of the blank, and the force exerted by the die is also illustrated in Figs. 38 to 40, inclusive, as effective to displace the metal of the blank laterally. If, therefore, a slot be formed on the blank 110 forward of that portion to which the die 115

120

125

130

is about to be applied (which, it will be understood from the foregoing description and from the disclosure made in my companion application hereinbefore referred to 5 is not always necessary), it will be evident that the formation of two type-characters in succession will cause a lateral displacement of the metal of the adjacent sides of each of such type-blanks sufficient to more 10 or less completely fill the upper part of the intervening slot 91, without forcing the metal displaced by either die over on to the opposite type-character; that is to say, the space formed at any point in the edge of 15 the blank should be sufficiently wide to receive the entire flowage induced laterally by the action of those dies which operate to produce the types on opposite sides of the slot and immediately contiguous thereto, 20 without causing the flowage rearward of the blank to interfere with a previously made type. In this manner I am enabled to form in the face of a typebar-blank a succession of selected or composed characters, or types, 25 with the adjacent faces of such types in such relation to each other as the component characters of a word represents without in any way interfering with the proper formation of such characters, while under those 30 conditions in which the flowage from each side comes in contact with each other in the preformed slot the types at the same time are maintained against movement longitudinally of the typebar more or less 35 throughout the length of the line of types in the measure that this contact occurs at each possible point of such contact along the bar.

By reference to Figs. 39 and 41, it will be noticed that the upper or face portions, only, 40 of the type-blanks are compressed, and that the bases of such type-blanks are substantially unaffected by the action of the dies.

In Fig. 39 the faces of the finished type are illustrated as being shaved by the cutter 45 *y*, for the purpose of bringing the surfaces of all the types of the typebar into a common plane. In Figs. 40 to 42, inclusive, the action of the cutters *z* and *z'* is illustrated, for trimming the sides of finished types and 50 removing the surplus metal forced beyond the planes of the sides of the typebar-blank by the action of the character-forming dies. This operation is necessary for the purpose of permitting the finished typebars to be 55 properly assembled and locked up in a form.

In Figs. 43 to 54, inclusive, I have illustrated, on a larger scale, the action upon the typebar-blank of tools suitable for shaping successive portions of the blank to form several different kinds of characters, usually 60 employed in a type-forming, composing machine. The cutters *r*, while operative to face the upper edges of successive portions along the blanks, are not all of the same character, 65 and by varying the lengths of the cutting-

edges of these tools, and the positions of the same, I am enabled to correspondingly vary the facing of the upper edges of sections of the typebar-blank of the same, or different, lengths. In a similar manner the tools *s* are 70 adapted to face portions of a greater or less length, and to a greater or less extent. It will be obvious, therefore, that the side-cutting tools should have their cutting edges of such lengths, and disposed in such positions, 75 as are adapted for properly trimming each respective portion according to the character to be made thereon. The portion for forming the letters "H", is faced (see Fig. 43) by a cutter *r* adapted for removing a small portion 95', of the upper edge of the blank 95, while the lower edge of the blank is faced at 95'', by the removal of a portion extending almost to the base thereof. The lengths of 80 the cutting edges of the facing tools also 85 correspond with the length of the typebar-blank which is fed by the selection of the key "H". In this case the top of the letter to be made will extend almost to the upper edge of the typebar-blank, and, hence, the 90 type-formative face thereof must be located in a corresponding position. In these views the edge of the main blank is represented as having been preliminarily cross-slotted, with 95 the result of setting off separate and individual type-blanks; but evidently this particular mode of treating the blank is not essential to the practical application of my present invention. As shown the next succeeding blank 96, is formed by the action of 100 two like cutters *r* and *s*, having their cutting edges of less length than those by which the edges of the blank 95 are faced. The typebar-blank, in this case, has been fed a distance corresponding to the size of the type-blank required for the formation of the letter "e", the faces formed by the removal of 105 the upper and lower edges of the type-blank being designated, respectively, by 96' and 96''. In this case the type-formative surface of the type-blank is centrally disposed, 110 relatively to the longitudinal sides of the typebar-blank. The third type-blank, shown in Fig. 43, is 115 illustrated as of a size necessitating the feeding of the typebar-blank a distance less than that required for the first type-blank, and greater than that necessary for the second type-blank. In this case the cutting edge of the cutter for facing the upper edge of the 120 type-blank 97, is of a length equal to the length of the typebar-blank fed for the formation of a type-blank for the letter "y". The cutter *s*, however, for facing the lower 125 edge of the type-blank 97, does not cut the face of the type-blank in a line parallel with the longitudinal axis of the typebar-blank, as is the case with the other cutters described with reference to Fig. 43, but obliquely to 130 the lower edge of the face of the type-blank 130

97, and intersecting the wall 91' of the slot 91, thereby leaving a portion of the type-blank face extending to the lower edge of such face, the portions removed being designated, respectively, by 97' and 97''. The fourth type-blank 98 is shown, as formed by feeding the typebar-blank a less distance than for any of the three previously described blanks 95, 96 and 97. In this case, 10 moreover, the cutting-tools *r* and *s* cut the type-blank in such a manner as to form a pyramidal type-blank having its apex below the surface of the typebar-blank, the faces formed by the cutting-tools being designated, 15 respectively, by 98' and 98''.

It will be apparent from the foregoing that the side-cutting tools correspond to the respective letters which they are adapted to aid the dies in shaping, precisely in the same 20 manner that the dies correspond to such characters, each of the cutters herein illustrated, with the exception of one, having its cutting edge of the characteristic length which the typebar-blank is fed for the production of the particular type corresponding 25 to such cutter. The number of different lengths which the typebar-blank may be fed will, of course, depend upon the number of sizes of the character to be formed in the 30 type-blanks, and in each instance the typebar-blank will, in the machine herein illustrated, be controlled by an indicator, or feed-actuator, corresponding in circumferential position with the die controlled thereby.

35 In Figs. 44 and 46 the respective characters are shown after being formed by the action of the appropriate dies upon the corresponding blanks illustrated in Figs. 43 and 45. The displacement of the metal, and the 40 consequent filling of the saw-slots, are clearly illustrated, the fourth formation being shown as having its face a considerable distance below the faces of the preceding characters, and constituting the blank or "space" 45 character.

In Fig. 46, and in Figs 52 to 54, inclusive, the result of the action of the respective dies upon the corresponding blanks is clearly illustrated, and it will be evident that only 50 in the upper portions of the type-blanks is there any considerable amount of flowage, the broad bases of these type-blanks being substantially unaffected by the action of the respective dies.

55 I am thus enabled to produce from a typebar-blank of suitable composition, and preferably of relatively-ductile metal, a typebar having a succession of individually-characteristic, composed types, which typebar is in 60 the typographic art a perfect substitute for any similar line of types, whether made up of separate pieces or an integral structure, and whether set up by hand or by any of the mechanical, type-composing machines here- 65 tofore known in the art.

It is obvious that my invention is not limited in character, as it is of the pioneer class and comprehends, broadly, any and all means whereby type or other characters are impressed or produced on suitable blanks by 70 subjecting the material of the blank to a rolling treatment and in which there is included a preliminary preparation of the surface involving the formation of a flowage space produced in any way, to accommodate the 75 displacement of the material under the action of the type or other character-formative devices.

It is also obvious that by the omission of certain parts of the machine, blanks may be 80 produced having suitably-shaped faces or blank-segments, each separated from the other, and that these segments may be impressed or stamped in another machine equipped with proper impressors or dies. 85

No claim is herein made to the peculiar means employed for actuating the latches, nor to the means for coupling and uncoupling the gear 33 with and from the internal-gear 38, as these parts, individually considered, are not of my invention. 90

One of the advantageous results obtained by means of my present improvement, relates to the particular mode of action of each type die upon that portion of the blank 95 acted upon by such die, since when my improved machine is operated at the speeds ordinarily required, for commercial work, the blow of rolling impression exerted upon the metal naturally and necessarily so affects 100 the metal as to develop therein such a degree of heat, especially in that portion which is to form the finished type then in process of formation, as will materially promote the typeforming operation through a reduction 105 of the cohesive resistance of said portion of the mass being operated upon.

Having thus described my invention, I claim—

1. The combination, with means for sustaining a blank, of means acting upon such blank to remove material from one point without adding it to the mass at an adjacent point and thereby form a reduced portion, and means for subsequently impressing said 115 blank adjacent to such reduced portion without disturbing a previously-impressed portion.

2. The combination, with means for sustaining a blank, of means acting upon such blank to remove material from one point without adding it to the mass at an adjacent point and thereby form a reduced portion; means for subsequently impressing the blank adjacent to such reduced portion without 120 disturbing a previously-impressed portion; and means, controlled by a key or lever, for actuating said reducing and impression means. 125

3. The combination, with a blank-carrier, 130

of a tool for removing material from one point without adding it to the mass at an adjacent point and thereby reducing the blank, and a tool for subsequently stamping the blank adjacent to the reduced portion thereof without disturbing a previously stamped portion.

4. The combination, with a blank-carrier, of a tool for removing material from one point without adding it to the mass at an adjacent point and thereby reducing the blank to form a set-off portion; a tool for subsequently stamping said set-off portion without disturbing a previously stamped portion; and means for actuating said tools.

5. The combination, with means for sustaining the material, of a tool for removing material from one point without adding it to the mass at an adjacent point and thereby forming a set-off portion; a stamping or impressing tool; and mechanism for successively actuating said tools into engagement with the blank without disturbing a previously-stamped portion.

6. The combination, with means for sustaining the material, of means for removing material from one point without adding it to the mass at an adjacent point and thereby forming a set-off portion; means for subsequently stamping or impressing the material without disturbing a previously stamped portion; and a movable carrier for such reducing and stamping means.

7. The combination, with a blank-holder, of a movable carrier; blank-reducing and impressing means carried by said carrier; and operative for removing material from one point without adding it to the mass at an adjacent point and also operative for impressing the blank adjacent to such reduced portion and mechanism for automatically actuating the blank reducing and impressing means successively into engagement with the blank without disturbing a previously stamped portion of the blank.

8. The combination, with a blank-holder, of means for removing material from one point in the blank without adding it to the mass at an adjacent point and thereby forming a set-off portion or blank-segment suitable to receive an impression.

9. The combination, with a blank-holder, of means for removing material from one point in the blank without adding it to the mass at an adjacent point and thereby forming a set-off portion or blank-segment, and means for subsequently facing said segment.

10. The combination, with a blank-holder, of means for reducing the blank to form a set-off portion or blank-segment; means for subsequently facing said segment; and means for cleaning said segment.

11. The combination, with means for sustaining a blank, of a movable body; means carried by said body for reducing the blank

to form a set-off portion or blank-segment adjacent to the reduced portion; and means, also carried by the movable body, for subsequently shaping such set-off portion to a form suitable to receive an impression.

12. The combination, with a blank-holder, and means for actuating the same, of a turret; a tool carried by the turret for reducing the blank to form a set-off portion or blank-segment; and rotary tools, also carried by the turret, for subsequently shaping such set-off portion to a form suitable to receive an impression.

13. The combination of a blank-carrier; a movable body; a tool carried by said body for reducing the blank to form a set-off portion; a series of tools, also carried by said body, for subsequently shaping said set-off portion to a form suitable to receive an impression; and means controlled by a key or lever for actuating said tools.

14. The combination of a blank-carrier; a movable body; means carried by said body and set in action by a key or lever for imparting a variable-feed to said blank-carrier; and means, also carried by said body, and controlled by such key or lever for shaping a portion of the blank to a relatively pyramidal form suitable to receive an impression.

15. The combination, with a movable body, of a blank-carrier, and variable-stroke feed-mechanism therefor; means carried by said body for shaping a portion of the blank to a relatively pyramidal form suitable to receive an impression; and an impressor also carried by said body for subsequently acting upon such portion.

16. The combination of a blank-carrier; a movable body; a series of tools for shaping a portion of the blank to a form suitable to receive an impression; an impressor for subsequently acting upon such portion; and means for trimming the blank to its proper dimensions after it has been impressed.

17. A machine comprising the following instrumentalities or organisms: viz., a blank-carrier; means for imparting a variable-feed to such carrier; a movable body, and a slot-forming reducing-tool; a series of character-shaping tools; and a feed-indicator carried by said body.

18. The combination, with a movable body and a series of character-shaping tools mounted thereon, of a starting device carried by one of said tools; a series of stops; and a series of keys controlling the movements of said stops.

19. The combination, with a movable body and a series of character-shaping tools mounted thereon, of a blank-carrier; a variable-speed actuator for said carrier; a starting device carried by one of the character-shaping tools; a key-board and keys; a series of stops; and means intermediate the keys

and stops whereby the key selected will advance the stop corresponding thereto into the plane of motion of said starting device.

20. In a machine of the class specified, the combination, with a blank-carrier for carrying a type-bar blank, of reducing means for reducing a longitudinal portion of the face of said blank to form a solid type-blank in advance of such reduced portion; character-forming means for forming a type-character in the face of said type-blank without disturbing a previously-formed type; and means for actuating said reducing means and character-forming means to a working position with respect to said type-bar blank.

21. In a machine of the class specified, the combination, with a blank-carrier for carrying a type-bar blank, of a slot-forming reducing-tool for transversely slotting the face 20 of said blank to form a type-blank in advance of said slot; a character-forming tool for forming a type-character in the face of said type-blank without disturbing a previously-formed type; and means for actuating said tools, respectively, to a working position with respect to said type-bar blank.

22. In a machine of the class specified, the combination, with blank-feeding mechanism operative for intermittently advancing a type-bar blank, of a slot-forming reducing-tool for transversely slotting the face of said blank to form a type-blank in advance of said slot; a character-forming tool for forming a type-character in the face of said type-blank without disturbing a previously-formed type; and means for actuating said tools, respectively, to a working position with respect to said type-bar blank.

23. The combination, with a blank-carrier, of means acting upon the blank to form a set-off portion; means for facing an edge of said set-off portion; and means for subsequently impressing said set-off portion.

24. The combination, with a blank-carrier, of means acting upon the blank to form a set-off portion; a pair of tools for facing non-contiguous portions of said set-off portion; and a tool for subsequently impressing said set-off portion.

25. In a machine of the class specified, the combination, with a blank-carrier for carrying a type-bar blank, of a slot-forming reducing-tool for transversely slotting the face of said blank to form a type-blank in advance of said slot; a shaving-tool for shaving the face of the type-blank; and means for successively actuating said tools, respectively, to a working position with respect to said type-bar blank.

26. The combination with, a blank-carrier, of means acting upon the blank to form a set-off portion; a tool for cleaning the face of said set-off portion; a tool for subsequently impressing said set-off portion; and means for actuating said tools.

27. The combination, with a blank-carrier, of reducing means acting upon the face of the blank to form a character-blank adjacent to the reduced portion; a tool for facing an upper edge of the character-blank; a tool for cleaning or shaving the face of the character-blank; a tool for forming a character in the face of said blank; and means for successively actuating said tools.

28. The combination, with a blank-carrier, of a reducing-tool for transversely slotting the blank to form a character-blank adjacent to said slot; a tool for forming a character in said blank; a tool for shaving the face of said character; and means for successively actuating said tools, respectively, into and out of engagement with said blank.

29. In a machine of the class specified, the combination, with a blank-carrier for carrying a type-bar blank, of a slot-forming reducing-tool for transversely slotting the face of said blank to form a type-blank in advance of said slot; a rotary character-forming tool for forming a type-character in the face of said type-blank; and a tool-carrier operative for carrying said tools, respectively, to a working position with respect to the type-bar blank.

30. The combination, with a blank-carrier, of reducing means acting upon the blank to form a set-off portion; a rotary tool for facing an edge of said set-off portion; a rotary impresser for impressing said set-off portion; and a movable body carrying said tools.

31. The combination, with a blank-carrier, of a tool for transversely slotting the blank to form a set-off portion; a pair of rotary tools for removing non-contiguous portions of upper edges of the set-off portion; a rotary-impresser for forming an impression in said set-off portion; and a rotary-turret adapted for successively carrying said tools, respectively, into and out of engagement with said set-off portion.

32. The combination, with a blank-carrier, of a reducing-tool for transversely slotting the face of the blank to form a set-off portion; a pair of rotary tools for facing non-contiguous portions of said set-off portion; a tool for cleaning the face of said set-off portion; an impresser for impressing said set-off portion; a tool for reducing the face of the impression; and a movable body carrying said tools.

33. The combination, with a blank-carrier, of means acting upon the blank to form a reduced portion; a tool for subsequently impressing the blank; means for actuating said tool; and a pair of tools in position and adapted for facing the sides of the finished impression to remove surplus material therefrom.

34. The combination, with a blank-carrier, of a plurality of shaping tools in position

and adapted for conjointly forming a character in a segment of the face of said blank; and means for successively actuating said tools, respectively, into and out of engagement with said blank-segment.

35. The combination, with a blank-carrier, of a plurality of tools in position and adapted for conjointly forming a character in a segment of the face of said blank; and a rotary 10 turret carrying said tools, and adapted for successively actuating said tools, respectively, into and out of engagement with said blank-segment.

36. The combination, with a blank-carrier, 15 of a slot-forming reducing-tool for transversely slotting the face of said blank to form a blank-segment in advance of said slot; a plurality of shaping-tools in position and adapted for conjointly forming a character 20 in the face of said blank-segment; and a rotary turret carrying said tools, and adapted for successively actuating said tools, respectively, into and out of engagement with said blank-segment.

25 37. The combination, with a blank-carrier, of two series of shaping-tools; key-controlled starting means for selectively bringing a pair of corresponding tools, one of each series, into position for operating upon the blank; 30 and means for actuating said selected tools into and out of engagement with a segment of said blank and in a predetermined order.

38. The combination, with a blank-carrier, 35 of a series of side-facing tools; a series of character-forming tools; starting means for selectively bringing a side-facing tool and the corresponding character-forming tool into position for operating upon the blank; and means for actuating said tools into and out 40 of engagement with a segment of said blank.

39. The combination, with a blank-carrier, 45 of a series of side-cutting tools; a series of character-forming tools movable separately from the side-cutting tools; and corresponding, respectively, in number and position with said side-cutting tools; starting means for selectively bringing a side-cutting tool and the corresponding character-forming tool into position for operating upon the blank; 50 and means for actuating said tools successively into and out of engagement with a segment of said blank.

40. The combination, with a blank-carrier, 55 of a reducing-tool for transversely slotting the face of the blank to form a set-off portion adjacent to said slot; a series of tools adapted each for facing an edge of the set-off portion; a series of impressors for forming each an impression in the set-off portion; 60 starting means for selectively bringing a side-facing tool and the corresponding impressor into position for operating upon the set-off portion; and means for successively actuating the reducing-tool and the selected 65 side-facing tool and impressor into and out

of engagement with the said set-off portion.

41. The combination, with a blank-carrier, 70 of two series of character-shaping tools having the tools of each series rotative in unison and movable separately from the tools of the other series; starting means for selectively bringing a pair of corresponding tools, one of each series, into position for operating upon the blank; and means for actuating 75 said selected tools into and out of engagement with the blank.

42. The combination, with a blank-carrier, 80 of two series of character-shaping tools having the tools of each series rotative in unison and movable separately from, and in a plane common to, the tools of the other series, and also having the tools of each series corresponding, respectively, in number and circumferential position with the respective 85 tools of the other series; starting means for selectively bringing a corresponding tool of each series into position for operating upon the blank; and means for actuating said tools into and out of engagement with the blank. 90

43. The combination, with a blank-carrier, 95 of a reducing-tool for acting upon the face of the blank to form a set-off portion; two series of tools adapted, respectively, for facing non-adjacent portions of upper edges of the set-off portion, and having the tools of each series rotative in unison and movable separately from the tools of the other series; a series of impressors for forming each an impression, and rotative in unison, 100 and movable separately from the said facing-tools; starting means for selectively bringing corresponding tools, one of each of said several series, into position for operating upon the blank; and means for successively actuating the reducing-tool, the selected facing-tools and the impressor into and out of engagement with the said set-off portion.

44. The combination, with a blank-carrier, 105 of a pair of tool-carriers connected for rotation in unison and in the same direction; a plurality of character-shaping tools secured to each of said tool-carriers, one set of tools corresponding, respectively, in number and position with the respective tools of the other tool-carrier; starting means for selectively bringing a tool of one of said series 110 into position for operating upon the blank, and thereby bringing the corresponding tool of the other of said series into position for operating upon said blank; and a rotary-turret carrying said tool-carriers, and operatively connected therewith for bringing a selected tool of each of said tool-carriers 115 into engagement with the blank. 120

45. In a key-controlled machine of the class specified, the combination, with a type-forming mechanism embodying a die-carrier 125 a type-forming die, and reducing means for removing material from one point in the 130

typebar-blank without adding it to the mass at an adjacent point, of a blank-carrier for carrying a type-bar blank, and means for actuating one of said carriers in a curvilinear path relatively to the other to effect a rolling engagement between the type-bar blank and the die.

46. In a machine of the class specified, the combination, with a type-forming mechanism embodying a die-carrier a type-blank-rolling type-die and reducing means for removing material from one point in the typebar-blank without adding it to the mass at an adjacent point, of a blank-carrier for carrying a type-bar blank, and means for actuating one of said carriers relatively to the other in a curvilinear path to effect a rolling engagement between said bar and the type-die, and thereby displace a portion of the bar in the direction of such rolling movement, and also to form a character.

47. In a machine of the class specified, the combination, with a type-forming mechanism embodying a die-carrier and a type-blank-rolling type-die, of a blank-carrier for carrying a type-bar blank, and means for actuating one of said carriers relatively to the other in a curvilinear path transverse to the type-bar blank to effect a rolling engagement between said bar and the die, and thereby displace a portion of the bar in the direction of such rolling movement, and also to form a character.

48. In a machine of the class specified, the combination, with a type-forming mechanism embodying a die-carrier a type-blank-rolling type-die and reducing means for removing material from one point in the typebar-blank without adding it to the mass at an adjacent point, of a blank-carrier for carrying a type-bar blank, and means for actuating one of said carriers in a curvilinear path relatively to the other to effect a rolling engagement between the type-die and one type-blank segment only of said type-bar blank without disturbing the preceding segment of said type-bar blank.

49. In a machine of the class specified, the combination, with a type-forming mechanism embodying a die-carrier a type-blank-rolling type-die movable in a curvilinear path and reducing means for removing material from one point in the typebar-blank without adding it to the mass at an adjacent point, of a blank-carrier for carrying a type-bar blank, and means for rolling said die in contact with one type-blank segment only of said type-bar blank without disturbing the preceding segment of said type-bar blank.

50. In a machine of the class specified, the combination, with a type-forming mechanism embodying a die-carrier a type-blank-rolling type-die movable in a curvilinear path and reducing means for removing ma-

terial from one point in the typebar-blank without adding it to the mass at an adjacent point, of a blank-carrier for carrying the type-bar blank, and means for rolling said die in contact with one type-blank segment only on the edge of said type-bar blank without disturbing the preceding segment of said type-bar blank.

51. In a machine of the class specified embodying mechanism for effecting a working engagement between a type-forming tool and a type-bar blank to thereby form a type in the blank, the combination, with a carrier for the type-bar blank, of a plurality of type-forming tools, and means for selectively actuating said tools in cycloidal paths each to a working position.

52. In a machine of the class specified embodying mechanism for effecting a working engagement between a type-die and a type-bar blank to thereby form a type in the blank, the combination, with a carrier for the type-bar blank, of a plurality of type-dies, and means for selectively actuating said dies in cycloidal paths each to a working position.

53. In a machine of the class specified embodying mechanism for effecting a working engagement between a type-forming tool and a type-bar blank to thereby form a type in the blank, the combination, with a blank-carrier for a type-bar blank, of a tool-carrier; a plurality of type-forming tools; means for selectively actuating said tools in cycloidal paths each to a working position; and means for imparting a feed movement to one of said carriers.

54. In a machine of the class specified embodying mechanism for effecting a working engagement between successively-selected type-dies and a type-bar blank to thereby form a series of types in the blank, the combination, with a carrier for a type-bar blank, of a plurality of type-dies; selecting means for selecting said dies one at a time; and means for successively actuating said selected dies in cycloidal paths each to a working position.

55. The combination, with a blank-carrier, of a pair of corresponding separately-movable character-shaping tools, and means for actuating said tools in cycloidal paths into and out of engagement with a segment of the blank.

56. The combination, with a blank-carrier, of a pair of corresponding separately-movable character-shaping tools, and means for actuating said tools successively in trochoidal paths into and out of engagement with a segment of the blank.

57. The combination, with a blank-carrier, of a pair of corresponding separately-movable character-shaping tools, and means for successively actuating said tools, respectively, in prolate and curtate epitrochoidal

- paths into and out of engagement with a segment of the blank.
58. The combination, with a blank-carrier, of a pair of corresponding separately-movable character-shaping tools, and means for successively actuating said tools, respectively, in prolate and curtate hypotrochoidal paths into and out of engagement with a segment of the blank. 70
- 10 59. The combination, with a blank-carrier, of a pair of corresponding separately-movable character-shaping tools, and means for actuating said tools successively in epicycloidal paths subtending similar orbital arcs, and into and out of engagement with a segment of the blank. 75
- 20 60. The combination, with a blank-carrier, of a pair of corresponding separately-movable character-shaping tools, and means for actuating said tools successively in hypocycloidal paths subtending similar orbital arcs, and into and out of engagement with a segment of the blank. 80
- 25 61. The combination, with a blank-carrier, of a pair of corresponding separately-movable character-shaping tools, and means for actuating said tools successively in epicycloidal paths subtending similar concentric orbital arcs, and into and out of engagement with a segment of the blank. 85
- 30 62. The combination, with a blank-carrier, of a pair of corresponding separately-rotative character-shaping tools, and means for actuating said tools in epicycloidal paths subtending similar orbital arcs, and into and out of engagement with a segment of the blank. 90
- 35 63. The combination, with a blank-carrier, of a pair of corresponding separately-movable character-shaping tools, and means for actuating said tools in a common plane and in epicycloidal paths subtending similar orbital arcs, and into and out of engagement with a segment of the blank. 95
- 40 64. The combination, with a blank-carrier, of a character-shaping tool, and means for actuating said tool in a trochoidal path into and out of engagement with a segment of the blank. 100
- 45 65. The combination, with a blank-carrier, of a character-shaping tool, and means for actuating said tool in a prolate trochoidal path into and out of engagement with a segment of the blank. 105
- 50 66. The combination, with a blank-carrier, of a character-shaping tool, and means for actuating said tool in a prolate hypotrochoidal path into and out of engagement with a segment of the face of the blank. 110
- 55 67. The combination, in a machine of the class specified embodying a tool-carrier a series of character-shaping tools carried thereby, reducing means for reducing a transverse portion of the face of the blank without adding material to the face of an adjacent portion of the blank, and a blank-carrier for carrying a character-bar-blank, of means for actuating one of said carriers transversely of the other, and means for shifting one of said carriers transversely of said transverse movement. 115
- 60 68. The combination, in a machine of the class specified embodying a tool-carrier a series of type-shaping tools carried thereby, reducing means for reducing a transverse portion of the face of the blank without adding material to the face of an adjacent portion of the blank, and a blank-carrier for carrying a typebar-blank; of means for actuating one of said carriers transversely of the other, and means for shifting one of said carriers perpendicularly of said transverse movement. 120
- 65 69. The combination, in a machine of the class specified embodying a tool-carrier a series of type-shaping tools carried thereby, reducing means for reducing a transverse portion of the face of the blank without adding material to the face of an adjacent portion of the blank, and a blank-carrier for carrying a typebar-blank, of means for actuating the tool-carrier transversely of the blank-carrier, and means for shifting one of said carriers transversely of such transverse movement. 125
- 70 70. The combination, in a machine of the class specified embodying a tool-carrier a series of type-shaping tools carried thereby, reducing means for reducing a transverse portion of the face of the blank without adding material to the face of an adjacent portion of the blank, and a blank-carrier for carrying a typebar-blank to be operated upon by said tools to form a typebar, of means for actuating the tool-carrier transversely of the blank-carrier, and means for shifting the blank-carrier transversely of the tool-carrier. 130
- 75 71. The combination, in a machine of the class specified embodying a tool-carrier and a series of type-shaping tools carried thereby, and reducing means for reducing a transverse portion of the face of the blank without adding material to the face of an adjacent portion of the blank, of means for longitudinally actuating a typebar-blank to be operated upon by said tools to form a typebar, and means for actuating the tool-carrier transversely of such typebar-blank. 135
- 80 72. In a key-controlled machine of the class specified, the combination, with a blank-carrier for carrying a type-bar blank, of a slot-forming reducing-tool for transversely slotting the face of said blank to form a type-blank in advance of said slot; without adding removed material to an adjacent portion of the face of the blank; a character-forming tool for forming a type-character in the face of said type-blank; a carrier for said character-forming tool; and means for actuating one of said carriers relatively to 140

the other to effect a working engagement between the type-blank and the character-forming tool.

73. In a key-controlled machine of the 5 class specified, the combination, with a blank-carrier for carrying a type-bar blank, of a slot-forming reducing-tool for transversely slotting the face of said blank to form a type-blank in advance of said slot; a character-forming tool for forming a type-character in the face of said type-blank; a carrier for said character-forming tool; and means for turning one of said carriers relatively to the other to effect a working engagement between the type-blank and the character-forming tool.

74. In a machine of the class specified, the combination, with a blank-carrier for carrying a typebar blank, of a slot-forming 20 reducing-tool for transversely slotting the face of said blank to form a type-blank in advance of said slot; a character-forming tool for forming a type-character in the face of said type-blank; and means for successively actuating said tools, respectively, into and out of engagement with said typebar-blank in parallel paths.

75. In a machine of the class specified, the combination, with a blank-carrier for 30 carrying a typebar-blank, of a slot-forming reducing-tool for transversely slotting the face of said blank to form a type-blank in advance of said slot; a character-forming tool for forming a type-character in the face 35 of said type-blank; and means for successively revolving said tools, respectively, into and out of engagement with said typebar-blank in parallel planes.

76. In a machine of the class specified, the 40 combination, with a blank-carrier for carrying a typebar-blank, of a reducing-tool operative for facing an upper edge of a type-blank segment of said typebar-blank and thereby reducing the area of the face of 45 said type-blank segment relatively to the base thereof; and means for actuating said reducing-tool into and out of engagement with said type-blank segment.

77. In a machine of the class specified, the 50 combination, with a blank-carrier for carrying a typebar-blank, of a side-cutting reducing tool operative for facing an upper edge of a type-blank segment of said typebar-blank and thereby reducing the area of the face of 55 said type-blank segment relatively to the base thereof; and means for actuating said side-cutting reducing-tool into and out of engagement with said type-blank segment.

78. In a machine of the class specified, the 60 combination, with a blank-carrier for carrying a typebar-blank, of a pair of reducing tools operative for facing non-contiguous portions of upper edges of a type-blank segment of said typebar-blank and thereby reducing the area of the face of said type-

blank segment relatively to the base thereof; and means for actuating said reducing-tools into and out of engagement with said type-blank segment.

79. In a machine of the class specified, the 70 combination, with a blank-carrier for carrying a typebar-blank, of a pair of side-cutting reducing-tools operative for facing the upper longitudinal edges of a type-blank segment of said typebar-blank and thereby reducing 75 the area of the face of said type-blank segment relatively to the base thereof; and means for successively actuating said side-cutting reducing-tools into and out of engagement with said type-blank segment. 80

80. In a machine of the class specified, the combination, with a blank-carrier for carrying a typebar-blank, of a slot-forming reducing-tool for transversely slotting the face of said blank to form a type-blank in advance of said slot; a side-cutting reducing-tool operative for facing an upper edge of 85 said type-blank to form a type-blank face of relatively small area as compared with the area of said type-blank face after the 90 impression of a character therein; a character-forming tool for forming a character in relief in the face of said type-blank; and means for successively actuating said tool respectively into and out of engagement 95 with said typebar-blank.

81. In a machine of the class specified, the combination, with a blank-carrier for carrying a typebar-blank, of character-forming means for forming a type-character in relief in the face of a type-blank segment of said typebar-blank; a shaving-tool for shaving the face of said type-character; and means for successively actuating said character-forming means and the shaving-tool 100 into and out of engagement with said type-blank segment.

82. In a machine of the class specified, the combination, with a blank-carrier for carrying a typebar-blank, of rotary character-forming means for forming a type-character in relief in the face of a type-blank segment of said typebar-blank; a shaving-tool for shaving the face of said type-character; and a rotary turret carrying said character-forming means and shaving-tool and adapted for successively actuating the same into and out of engagement with said type-blank segment. 110

83. The combination, with a blank-carrier for carrying a typebar-blank, of a cutting-tool adapted for facing an edge of said typebar-blank; means for normally revolving said tool in inoperative relation with said blank; and means for intermittently carrying said tool into engagement with said blank. 120

84. The combination, with a blank-carrier, of a tool operative for shaping a portion of the face of the blank; means for normally 130

revolving said tool in inoperative relation with said blank and blank-carrier; and means for intermittently actuating one of said members to effect a working engagement between the tool and the blank.

85. The combination, with a blank-carrier, of a tool operative for shaping a portion of the face of the blank; means for normally revolving said tool in inoperative relation with said blank; and means for intermittently carrying said tool into engagement with said blank.

86. The combination, with a blank-carrier, of a cutting-tool adapted for facing an edge of the blank; means for revolving said tool in an orbital path and in inoperative relation with said blank; and means for enlarging the orbital path of the tool for bringing the tool into operative relation with the blank for facing said blank.

87. In a machine of the class specified, the combination, with a blank-carrier for carrying a typebar-blank, of a rotary turret; a pair of tools normally carried by said turret in inoperative relation with said typebar-blank and adapted for shaping a portion of the face of said blank; and means for intermittently and successively carrying said tools into engagement with said blank.

88. The combination, with a blank-carrier, of a rotary turret; a slot-forming reducing-tool revolvable with said turret, and normally in inoperative relation with the blank, and adapted for transversely slotting the face of said blank to form a blank-segment; a tool carried by, and rotatable relatively to, said turret, and normally in inoperative relation with said blank, and adapted for shaping the face of said blank; and means for intermittently shifting said tools to their operative positions to carry said tools successively into engagement with said blank.

89. The combination, with a blank-carrier, of a main driving shaft; a turret secured to said shaft; a plurality of tool-carrying shafts journaled in said turret; an eccentrically-disposed stud in fixed relation with the main shaft and with the turret; a gear-wheel journaled on said stud; pinions secured, respectively, to the tool-carrying shafts, and in mesh with said gear-wheel, and having equal peripheral velocities; tools secured, respectively, to the tool-carrying shafts, and having corresponding rotative positions, and movable in a common plane transversely to the blank, and normally in inoperative relation with said blank; and means for intermittently rotating said gear-wheel and pinions to carry said tools successively into engagement with a segment of said blank.

90. The combination, with a blank-carrier, of a main driving-shaft; a turret secured to said shaft; a plurality of tool-car-

rying shafts journaled in said turret; an eccentrically-disposed stud in fixed relation with the main shaft and with the turret; a gear-wheel journaled on said stud; pinions secured, respectively, to the tool-carrying shafts, and in mesh with said gear-wheel, and having equal peripheral velocities; tools secured, respectively, to the tool-carrying shafts and having corresponding rotative positions, and movable in a common plane transversely of the blank, and normally in inoperative relation with said blank; an internal gear; a spur-wheel carried by one of the tool-carrying shafts and rotatable therewith, and longitudinally shiftable thereon; and means for intermittently shifting said shiftable spur-wheel into mesh with said internal gear, to rotate the tools and carry said tools successively into engagement with a segment of said blank.

91. The combination, with a blank-carrier, of a main driving-shaft; a turret secured to said shaft; a plurality of tool-carriers journaled in said turret; a gear-wheel journaled for rotation on the turret; pinions secured, respectively, to the tool-carriers, and in mesh with said gear-wheel, and having equal peripheral velocities; tools secured, respectively, to the tool-carriers, and having corresponding rotative positions, and movable transversely of the blank, and normally in inoperative relation with said blank; means for normally preventing rotation of one of the tool-carriers; and means for intermittently rotating said gear-wheel and pinions to carry said tools successively into engagement with a segment of said blank.

92. The combination, with a blank-carrier, of a main driving-shaft; a turret secured to said shaft; a tool-carrying shaft journaled in said turret; a tool carried by said shaft for rotation therewith, and movable transversely of the typebar-blank, and normally in inoperative relation with said blank; a brake for normally holding the tool-carrying shaft against rotation; and means for intermittently rotating said tool-carrying shaft in opposition to the power of the brake, to carry said tool into engagement with a segment of the blank.

93. The combination, with a blank-carrier, of a main driving-shaft; a turret secured to said shaft; a tool carrying shaft journaled in said turret, and having a peripheral cam-face; a tool carried by said shaft for rotation therewith, and movable transversely of the blank, and normally in inoperative relation with said blank; a spring-pressed brake normally in engagement with the cam-face of the tool-carrying shaft, for holding said shaft against rotation; and means for intermittently rotating said tool-carrying shaft in opposition to the

power of the brake, to carry said tool into engagement with a segment of said blank.

94. The combination, with a blank-carrier, of a main driving shaft; a turret secured to said shaft; a plurality of tool-carrying shafts journaled in said turret, and one of said shafts having a cam-face; a gear-wheel journaled for rotation on the turret; pinions secured, respectively, to the tool-carrying shafts, and having corresponding rotative positions, and movable transversely of the typebar-blank, and normally in inoperative relation with said blank; a slot-forming reducing-tool having a pivotal connection with the turret, and movable transversely of the blank; a spring-pressed brake carried by said slot-forming reducing-tool, and normally in engagement with the cam-face of the tool-carrying shaft, for holding said slot-forming reducing-tool in inoperative relation with the blank and for preventing rotation of said tool-carrying shaft; and means for intermittently rotating said gear-wheel and pinions in opposition to the power of the brake, to carry said tools successively into engagement with the blank.

95. The combination, with a blank-carrier, of a main driving-shaft; a turret secured to said shaft; a tool-carrier journaled in said turret, and having a peripheral cam-face; a tool secured to said carrier, and operative transversely of the blank, for shaping the face thereof, and normally in inoperative relation with the blank; a slot-forming reducing-tool having a pivotal connection with the turret, and operative for transversely slotting the face of the blank; a spring-pressed brake carried by said slot-forming reducing-tool, and normally in engagement with the cam-face of the tool-carrier, for holding said slot-forming reducing-tool in inoperative relation with the blank and for preventing rotation of said tool-carrier; and means for intermittently rotating said tool-carrier in opposition to the power of the brake, to carry said tools into engagement with the blank.

96. The combination, with a type-forming mechanism embodying reducing means for removing material from one point in the typebar-blank without adding it to the mass at an adjacent point, of feeding mechanism controlled by said type-forming mechanism and adapted for intermittently feeding a type-bar blank for presenting successive type-blank segments of said blank to the type-forming mechanism.

97. The combination, with type-forming turret mechanism embodying reducing means for removing material from one point in the typebar-blank without adding it to the mass at an adjacent point, of feeding mechanism controlled by said turret mechanism and adapted for intermittently feeding a type-bar blank for presenting successive

type-blank segments of said blank to the type-forming mechanism.

98. The combination, with a type-forming turret mechanism embodying reducing means for removing material from one point in the typebar-blank without adding it to the mass at an adjacent point, of feeding mechanism controlled by said turret mechanism and adapted for intermittently feeding a type-bar blank transversely of the plane of rotation of said turret mechanism for presenting successive type-blank segments of said blank to the type-forming mechanism.

99. The combination, with type-forming mechanism embodying reducing means for removing material from one point in the typebar-blank without adding it to the mass at an adjacent point, of step-by-step feeding mechanism controlled by said type-forming mechanism and adapted for intermittently feeding a type-bar blank for presenting successive type-blank segments of said blank to the type-forming mechanism.

100. The combination, with type-forming mechanism embodying reducing means for removing material from one point in the typebar-blank without adding it to the mass at an adjacent point, of variable-feed mechanism controlled by said type-forming mechanism and adapted for intermittently feeding a type-bar blank for presenting successive type-blank segments of said blank to the type-forming mechanism.

101. The combination, with a type-forming mechanism embodying reducing means for removing material from one point in the typebar-blank without adding it to the mass at an adjacent point and having a plurality of selectable type-dies, of feeding mechanism controlled by said type-forming mechanism and adapted for intermittently feeding a type-bar blank for presenting successive type-blank segments of said blank to the type-forming mechanism.

102. The combination, with a type-forming mechanism embodying reducing means for removing material from one point in the typebar-blank without adding it to the mass at an adjacent point and having a plurality of selectable type-dies, of selecting means controlling said respective dies; and feeding mechanism controlled in its operation by the positioning of the type-forming mechanism and adapted for intermittently feeding a type-bar blank for presenting successive type-blank segments of said blank to the type-forming mechanism.

103. The combination, with a type-forming mechanism embodying reducing means for removing material from one point in the typebar-blank without adding it to the mass at an adjacent point and having a plurality of selectable type-dies of different widths, of variable-feed mechanism controlled by said type-forming mechanism and having

- variable-feed movements proportionate to the widths of the respective selected type-dies and adapted for intermittently feeding a type-bar blank for presenting successive 5 type-blank segments of said blank to the selected type-dies of the type-forming mechanism.
104. The combination, with a type-forming mechanism embodying reducing means 10 for removing material from one point in the typebar-blank without adding it to the mass at an adjacent point and having a plurality of selectable type-dies of different widths, of variable - feed mechanism controlled by 15 said type-forming mechanism and having variable-feed movements that are multiples of a given unit of feed and are proportionate to the widths of the respective selected type-dies and adapted for intermittently feeding 20 a type-bar blank for presenting successive type-blank segments of said blank to the selected type-dies of the type-forming mechanism.
105. The combination, with a type-forming mechanism embodying reducing means 25 for removing material from one point in the typebar-blank without adding it to the mass at an adjacent point and having a plurality of type-dies, of feeding mechanism controlled by said type-forming mechanism and adapted for intermittently feeding a type- 30 bar blank for presenting successive type-blank segments of said blank to the type-forming mechanism, one member of one of 35 said mechanisms being movable relatively to a coöperating member of the other mechanism to effect a working engagement between a type-die and a type-blank.
106. The combination, with a type-forming mechanism embodying reducing means 40 for removing material from one point in the typebar-blank without adding it to the mass at an adjacent point and having a plurality of type-dies, of feeding mechanism controlled by said type-forming mechanism and adapted for intermittently feeding a type- 45 bar blank for presenting successive type-blank segments of said blank to the type-forming mechanism, one member of one of 50 said mechanisms being movable in a curvilinear path relatively to a coöperating member of the other mechanism to effect a rolling engagement between a type-die and a type-blank.
107. The combination, with type-forming mechanism embodying reducing means for removing material from one point in the typebar-blank without adding it to the mass at an adjacent point and having a tool-carrier 55 and a type-forming tool, of a blank-carrier for a type-bar blank; means for imparting an impression movement to one of said carriers to effect a working engagement between the type-forming tool and the type- 60 bar blank; and means for imparting a feed

movement to one of said carriers alternately with said impression movement to feed one of the carriers relatively to the other.

108. The combination, with type-forming mechanism embodying a die-carrier and a 70 type-die, of a blank-carrier for a type-bar blank; means for imparting a rolling impression movement to one of said carriers to effect a rolling engagement between the type-die and the type-bar blank; and means for 75 imparting a feed movement to one of said carriers alternately with said impression movement to feed one of the carriers relatively to the other.

109. The combination, with type-forming 80 mechanism embodying a tool-carrier a type-forming tool and reducing means for removing material from one point in the typebar-blank without adding it to the mass at an adjacent point, of a blank-carrier for a type- 85 bar blank; means for imparting intermittent feed movements to one of said carriers for presenting successive type-blank segments of said blank to the type-forming mechanism; and means for imparting impression movements to one of said carriers alternately with 90 said feed movements to effect a working engagement between the type-forming tool and successive type-blank segments without disturbing preceding segments of the type-bar 95 blank.

110. The combination, with type-forming mechanism embodying a die-carrier a plurality of dies and reducing means for removing material from one point in the typebar-blank without adding it to the mass at an adjacent point, of selecting means for said dies; a blank-carrier for a type-bar blank; means for imparting intermittent feed movements to one of said carriers for presenting 100 successive type-blank segments of said blank to the type-forming mechanism; and means for imparting impression movements to one of said carriers alternately with said feed movements to effect a working engagement 105 between each successive selected type-die and each successive type-blank without disturbing the preceding segments of the type-bar blank.

111. In a key-controlled machine of the 110 class specified, the combination, with a blank-carrier for a type-bar blank, of a die-carrier and dies; reducing means operative for reducing transverse portions of the face of said blank without adding material to adjacent portions of the face of said blank to form successive solid type-blanks separated by such reduced portions; means for intermittently feeding one of said carriers; and means for actuating one of said carriers relatively to the other to effect a working engagement between the solid type-blanks and the corresponding dies.

112. In a key-controlled machine of the 115 class specified, the combination, with a blank-

carrier for a type-bar blank, of a die-carrier and dies; slot-forming reducing means operative for transversely slotting the face of said blank without adding material to adjacent portions of the face of said blank to form successive type-blanks separated by such slots; means for intermittently feeding one of said carriers; and means for actuating one of said carriers relatively to the other to effect a working engagement between the type-blanks and the corresponding dies.

113. In a machine of the class specified, the combination, with a blank-carrier for a type-bar blank, of a die-carrier and dies; slot-forming reducing means operative for transversely slotting the face of said blank to form successive type-blanks separated by said slots; means for intermittently feeding one of said carriers; and means for actuating one of said carriers in a curvilinear path relatively to the other to effect a rolling engagement between the type-blanks and the corresponding dies.

114. In a key-controlled machine of the class specified, the combination, with a type-forming mechanism embodying a die-carrier a die and reducing means for reducing a transverse portion of the face of the blank without adding material to an adjacent portion of the face of said blank, of a blank-carrier for carrying a type-bar blank; means for actuating one of said carriers relatively to the other to effect a working engagement between the type-bar blank and the die; and means for imparting a feed movement to one of said carriers.

115. In a machine of the class specified, the combination, with a type-forming mechanism embodying a die-carrier and a type-blank-rolling type-die, of a blank-carrier for carrying a type-bar blank; means for actuating one of said carriers in a curvilinear path relatively to the other to effect a rolling engagement between the type-die and one type-blank segment only of said type-bar blank without disturbing the preceding segment of said type-bar blank; and means for imparting a feed movement to one of said carriers.

116. The combination, with a type-forming turret mechanism, of feeding mechanism operable by said type-forming turret mechanism and adapted for intermittently feeding a type-bar blank transversely of the plane of rotation of said turret mechanism for presenting successive type-blank segments of said type-bar blank to the type-forming mechanism.

117. The combination, with turret-mechanism carrying character-shaping and forming tools, of feeding-mechanism operable by said turret-mechanism and adapted for intermittently feeding a blank transversely of the plane of rotation of said turret-mech-

anism, for presenting successive segments 65 of said blank to the character-forming tools.

118. The combination, with character shaping and forming turret-mechanism, of variable-stroke feeding-mechanism operable by said turret-mechanism and adapted for 70 intermittently feeding a blank different lengths transversely of the plane of rotation of said turret-mechanism, for presenting successive segments of the blank to the character-forming mechanism. 75

119. The combination, with character-forming turret-mechanism, of feeding-mechanism operable by said turret-mechanism and adapted for intermittently feeding a character-bar blank transversely of the 80 plane of rotation of said turret-mechanism, for presenting successive segments of said character-bar blank to the forming mechanism; an internal-gear normally in inoperative relation with the character-forming 85 mechanism; and means for intermittently bringing said forming mechanism into operative relation with said fixed internal gear.

120. The combination, with character-forming turret-mechanism, of feeding-mechanism operable by said turret-mechanism and adapted for intermittently feeding a character-bar blank transversely of the plane of rotation of said turret-mechanism, for presenting successive segments of said 95 blank to the forming mechanism; a fixed internal-gear normally in inoperative relation with the character-forming mechanism; and selectively-operative means for intermittently bringing said character-forming mechanism into operative relation with said internal-gear at predetermined points in said gear. 100

121. The combination, with character-forming turret-mechanism, of feeding-mechanism operable by said turret-mechanism 105 and adapted for intermittently feeding a blank transversely of the plane of rotation of said turret-mechanism, for presenting successive segments of said blank to the character-forming mechanism; a fixed internal-gear concentric with the axis of, and normally in inoperative relation with, the character-forming mechanism; selectively-operative means for intermittently bringing said character-forming mechanism into operative relation with said fixed internal-gear at predetermined points in said gear. 110 and means for throwing said character-forming mechanism out of operative relation with said gear after a predetermined period of operation. 115 120

122. The combination, with character-forming turret-mechanism substantially as specified, of feeding-mechanism operable by said turret-mechanism and adapted for intermittently feeding a bar-blank transversely of the plane of rotation of said turret-mechanism, for presenting successive segments of said bar-blank to the forming 125

mechanism; a fixed internal-gear concentric with the axis of, and normally in inoperative relation with, the said character-forming mechanism; a series of starting devices 5 disposed at predetermined orbital points concentric with the axis of said forming-mechanism, and adapted, respectively, for bringing said forming-mechanism into operative relation with said gear at points in 10 said gear corresponding, respectively, with the orbital positions of said starting devices; and key-actuated devices for selectively actuating said starting devices.

123. The combination, with a character-forming turret-mechanism embodying a plurality of shaping tools adapted, respectively, for forming different characters, and also embodying means for actuating a feeding-mechanism different distances, of variable-stroke feeding-mechanism operable by said actuating means and adapted for intermittently feeding a bar-blank different lengths transversely of the plane of rotation of said turret-mechanism, for presenting successive 25 segments of said blank to the character-forming mechanism; starting means for selectively bringing any one of said tools into position for operating upon the bar-blank; and means for actuating said selected tool 30 into and out of engagement with a segment of said blank.

124. The combination, with character-forming turret-mechanism, embodying two series of shaping tools and also embodying 35 means for actuating a feeding-mechanism different distances, of variable-stroke feeding-mechanism operable by said actuating means and adapted for intermittently feeding a bar-blank different lengths transversely of the plane of rotation of said 40 turret-mechanism, for presenting successive segments of said bar-blank to the character-forming mechanism; starting means for selectively bringing a pair of corresponding 45 tools, one of each series, into position for operating upon the blank; and means for actuating said selected tools into and out of engagement with a segment of said bar-blank and in a predetermined order.

125. The combination, with type-forming mechanism having a type-forming tool, of a feed-indicator movable with and controlled in its operation by said tool and having a feed dimension corresponding in feed value 55 with that of said tool.

126. The combination, with type-forming mechanism having a type-die, of a feed-indicator movable in synchronism with said type-die and having a feed dimension corresponding in feed value with the width of said die.

127. The combination, with type-forming mechanism having a rotary type-die, of a feed-indicator movable with and controlled 65 in its operation by said type-die and having

a feed dimension corresponding in feed value with the width of said die.

128. The combination, with type-forming mechanism having a type-die movable in a cycloidal path, of a feed-indicator movable 70 with and controlled in its operation by said type-die.

129. The combination, with type-forming mechanism having a type-die for forming a character of a predetermined width, of a selector 75 controlling said die; means for bringing said die to its working position; and a feed-indicator having a predetermined feed dimension corresponding in feed value with the width of said die and controlled in its operation by the positioning of said die.

130. The combination, with a type-forming mechanism having a set of type-dies for forming characters of different widths, of selecting means controlling said respective dies; means for bringing each selected die to its working position; and a plurality of feed-indicators each having a predetermined feed dimension corresponding in feed value with the width of one or more dies and each 85 controlled in its operation by the positioning of a corresponding type-die.

131. The combination, with a type-forming mechanism having a set of type-dies for forming characters of different widths the width of each die being a multiple of a given unit, of selecting means controlling said respective dies; means for bringing each selected die to its working position; and a plurality of feed-indicators controlling feed movements which are multiples of a given unit, and each feed-indicator having a predetermined feed dimension corresponding in feed value with the width of one or more dies and each controlled in its operation by the 95 positioning of a corresponding type-die.

132. The combination, with type-forming mechanism having a type-die for forming a character of a predetermined width, of a selector controlling said die; means for bringing said die to its working position; and a feed-indicator having a predetermined feed dimension corresponding in feed value with the width of said die and movable with, and controlled in its operation by the 100 positioning of, said die.

133. The combination, with type-forming mechanism having a type-die for forming a character of a predetermined width, of a selector controlling said die; means for bringing said die to its working position; and a feed-indicator having a predetermined feed dimension corresponding in feed value with the width of said die and movable in synchronism therewith.

134. The combination, with type-forming mechanism having a type-die for forming a character of a predetermined width, of a selector controlling said die; means for bringing said die to its working position; 125

- means for actuating the main carrier and organized and timed for selecting and controlling the operation of said subordinate carrier and thereby so locating such subordinate carrier in positions with relation to the main carrier as to bring the successively selected dies to the working point and cause the impression of the blank by a turning movement of the blank and the selected dies, the one 5 relatively to the other; and means for successively feeding the blank in consonance with the line-space value of the selected dies. 166. In a machine organized for making impressions, the combination with a support 15 for a line of type blank, of selective impression devices; means for bringing a selected impression device to the working point of the machine; means for effecting a rolling movement between the selected impression 20 device and the blank at such working point to progressively vary the angular relation of the impression device and the blank during the progress of impressing the latter, and means organized and timed for determining 25 the feed movement of the blank in consonance with the line-space value of the selected impression device and for advancing the blank through the distance so determined. 167. In a machine organized for making impressions, the combination with a support 30 for a line of type blank, of selective impression devices; means for bringing a selected impression device to the working point of 35 the machine; means for effecting a rolling working movement between the selected impression device and the blank at such working point transversely to the latter; and feed mechanism comprising means organized and 40 connected for determining the feed movement of the blank in consonance with the line space value of the selected impression device and for advancing the blank through the distance so determined. 168. In a machine organized for making impressions, the combination with a support 45 for a blank of selective impression devices; means for bringing a selected impression device to the working point of the machine; means for effecting a rolling working movement 50 between the selected impression device and a blank at such working point transversely to such blank; and feed mechanism having means organized and timed for determining the feed movement of the blank in consonance with the line-space value of the selected die and for advancing the blank through the distance so determined during the period between the 55 making of the successive types. 169. In a machine organized for making impressions; the combination with a support 60 for a line of type blank, of selective dies; means for bringing a selected die to the 65 working point of the machine; means for effecting a rolling movement between the selected impression die and the blank at such working point transversely to the latter; and feed mechanism comprising means organized and connected for determining the feed movement of the blank in consonance with the line-space value of the selected die, and for advancing the blank through the distance so determined during the period between the 70 making of successive types. 170. In a machine organized for making impressions, the combination with a support for a line of type blank, of selective dies; means for bringing a selected die to the working point of the machine; means for effecting a working movement between the selected die and a blank at such working point to progressively vary the angular relation of the die and the blank during the progress of impressing the latter; and means organized 75 and timed for determining the feed movement of the blank in consonance with the line-space value of the selected die and for advancing the blank through the distance so determined. 171. In a machine organized for making impressions, the combination with a support for a blank of selective dies; means for bringing a selected die to the working point of the machine; means for effecting a rolling working movement between the selected die and a blank at such working point transversely to such blank; and feed mechanism having means organized and connected for determining the feed movement of the blank in consonance with the line space value of the selected die and for advancing the blank through the distance so determined. 172. In a machine organized for making impressions, the combination with a support for a line of type blank, of selective dies; means for bringing a selected die to the working point of the machine; means for effecting a rolling working movement between the selected die and a blank at such working point transversely to such blank; and feed mechanism comprising means organized and timed for determining the feed movement of the blank in consonance with the line-space value of the selected die and for advancing the blank through the distance so determined during the period between the 90 making of the successive types. 173. The combination in a type-making mechanism embodying type dies for operating upon a line of type blank, of means for imparting to one of said members during the making of each type a rapid impression movement relatively to the other to effect a rapid working engagement between the die 100 and the blank for changing the normal temperature of the latter. 174. The combination, in a type-making

- mechanism embodying type dies for operating upon a typebar blank, of means for imparting to one of said members during the making of each type a rapid impression 5 movement relatively to the other to effect a rapid working engagement between the die and the blank and thereby effect the heating of the blank during the making of the type.
175. The combination with a die carrier, 10 of a plurality of type-making dies mounted thereon; a blank support; and means for imparting to the die carrier a rapid and continuously progressive movement whereby to change the normal temperature of the blank.
176. The combination with a plurality of 15 selective dies for rolling a line of type blank, of means for effecting a rapid working engagement between each selected die and the blank, whereby the blank is heated during 20 the formation of the type and the action of the die in forming the type is facilitated.
177. In a key-controlled mechanism, the 25 combination with type-making mechanism embodying a die carrier having type-making dies mounted thereon, of a support for a line of type blank; and means for actuating type-making members in a curvilinear path, the one relatively to the other, to effect during 30 each type-forming operation a rapid rolling engagement between the blank and the die and the heating of the material of the blank.
178. In a machine organized for making 35 impressions, the combination with a support for a blank, of selective impression devices; means for bringing the selected impression device to the working point of the machine; means for effecting a rapid working engagement between the selected impression device 40 and a blank at such working point to thereby effect the heating of the blank at that point, and the progressive variation of the angular relation of the impression device to the blank during the progress of impressing 45 the blank; and means organized and adapted for determining the feed movement of the blank in consonance with the line-space value of the selected impression device and for advancing the blank through the distance 50 so determined.
179. The combination with a series of blank-heating type-making dies, of a support for a line of type blank, and mechanism for causing the rapid engagement of 55 each selected die in succession with a blank in the support to thereby subject the material of the blank under the working die to the rapid working of the latter and effect the diminution of the internal resistance in the 60 material lying in the upper edge of the blank by reason of the heat generated.
180. A type-blank holder, a metallic type-blank therein, and means to heat the upper projecting edge of the type-blank.
181. The combination with a type blank 65 holder and a metallic type-bar blank therein, of means for raising the temperature of the successive portions of the edge of the said type-bar blank entering into the respective types.
182. A type blank holder and metallic type blank therein and means to simultaneously heat an edge of the blank and form a type on such edge.
183. A type blank holder and metallic 75 type blank therein and means to simultaneously heat an edge of the blank and form types on such edge in succession.
184. In a machine organized for making impressions, the combination with a support 80 for a blank, of selective impression devices, means for bringing a selected impression device to the working point of the machine, means for effecting a rapid working engagement between the selected impression device 85 and a blank at such working point to thereby effect the heating of the blank at that point and the progressive variation of the angular relation of the impression device and the blank during the progress of the impressing 90 of the blank, and means organized and adapted for determining the feed movement of the blank in consonance with the line space value of the selected impression device and for advancing the blank through 95 the distance so determined.
185. In a machine organized for making impressions, the combination with a support 100 for a blank, of selective impression devices, means for bringing a selected impression device to the working point of the machine, means for effecting a rapid rolling engagement between the selected impression device and a blank at such working point transversely to such blank to thereby effect the 105 heating of the blank at that point and the progressive variation of the angular relation of the impression device and the blank during the progress of the impressing of the blank, and means organized and adapted for 110 determining the feed movement of the blank in consonance with the line space value of the selected impression device and for advancing the blank through 115 the distance so determined.
186. The combination, in a type-making mechanism embodying a type-die for operating upon a typebar-blank, of means for imparting to one of said members, viz. the die and the blank, an impressing movement 120 relative to the other to effect a working engagement between the die and the blank sufficiently rapid to thereby effect the heating of the blank during the making of the type.
187. The combination with a die-carrier, of a plurality of type-forming dies mounted thereon, a blank support, means for impart-

with it the subordinate carrier; means for supporting, at the working point, a blank for making a line of type; selective mechanism organized and connected for controlling the operation of the subordinate carrier on the main carrier and thereby so locate the subordinate carrier with relation to the main carrier when at the working point of the machine as to bring the selected impression device on such subordinate carrier to such point; and means for feeding the blank during the period between the making of successive impressions thereon.

160. In a machine organized for making impressions, the combination with a support for a typebar-blank, of selective type-forming impression devices; means for bringing a selected impression device to the working point of the machine; means for effecting a working movement between the selected impression device and a blank at such working point; and means organized and timed for determining the feed movement of the blank in consonance with the line space value of the selected impression device and for advancing the blank through the distance so determined during the period between the making of successive impressions.

161. In a machine organized for making impressions in succession, the combination with a main carrier and at least one subordinate carrier, of a plurality of impression devices having various line-space values, and some of which at least are located on the mentioned subordinate carrier, said subordinate carrier being movably supported on the main carrier; means for actuating the main carrier and for selectively operating the said subordinate carrier and bringing the subordinate carrier to the working point in working position relatively to said main carrier to thereby cause the rolling impression movement of the selected impression device and the blank one upon the other; means for supporting at such working point a blank for making a line of type in position to be operated upon by the selected impression device; and feed devices connected and operative for feeding the blank during the period between successive impressions in a direction transverse to such rolling impression movement.

162. In a machine organized for making impressions in succession, the combination with a main carrier and at least one subordinate carrier, of a plurality of selective impression devices of varying line-space values, and some of which at least are located on the mentioned subordinate carrier, said subordinate carrier being movably supported on the main carrier; mechanism for actuating the main carrier; means for supporting a line of type blank in position at the working point; selective mechanism or-

ganized and connected for selecting and controlling the operation of the said subordinate carrier and thereby so locating such carrier successively in working positions with relation to the main carrier as to bring the successively selected impression devices to the working point and cause the rolling of the blank by said selected impression devices at successive operations of the machine, and means for feeding the blank in consonance with the line-space values of the successively located impression devices respectively.

163. The combination with a main carrier and a plurality of selective dies, of at least one subordinate carrier having thereon a plurality of such dies and which is movably supported on the main carrier for bringing the selected dies in succession to a given working position in the machine; means for actuating the main carrier; means for supporting a line of type blank at the working point; selective mechanism operatively connected with the means for actuating the main carrier, and organized and timed for selecting and controlling the operation of said subordinate carrier, and thereby so locating such carrier successively in working positions with relation to the main carrier as to bring the successively selected dies to the working point and cause the impression of the blank by a rolling movement transversely thereof; and means for feeding the said blank.

164. The combination with a main carrier and a plurality of selective dies, of at least one subordinate carrier having thereon a plurality of such dies and which is movably supported on the main carrier for bringing a selected die to a given working position in the machine; means for actuating the main carrier; a support for a line of type blank; selective mechanism operatively connected with the means for actuating the main carrier and organized and timed for selecting and controlling the operation of said subordinate carrier and thereby so locating such carrier successively in working positions with relation to the main carrier as to bring the successively selected dies to the working point and cause the impression of the blank by a turning movement of the blank and of the selected die, the one relatively to the other; and means for feeding said blank.

165. The combination with a main carrier and a plurality of selective dies having various line-space values, of at least one subordinate carrier having thereon a plurality of such dies and which is movably supported on the main carrier for bringing a selected die to a given working position in the machine; means for actuating the main carrier; a support for a line of type blank; selective mechanism operatively connected with the

also embodying means for impressing the blank to form a type adjacent to such reduced portion.

152. In a typographic machine, the combination with a series of selective impression devices, of means for bringing selected devices one at a time to the working point of the machine; means for sustaining a blank to be operated upon at the working point;

10 means for impressing the blank and the particular impression device selected one upon the other to make an impression; a blank-feed embodying a pawl-and-ratchet device organized for making variable-length feed 15 strokes; and a series of feed faces connected for operation in consonance with said impression devices and having working positions corresponding to the line-space values, respectively, of said impression devices.

20 153. In a typographic machine, the combination with a series of selective impression devices, of means for bringing selected devices one at a time to the working point of the machine; means for sustaining a blank 25 to be operated upon at the working point; means for impressing the blank and the particular impression device selected one upon the other to make an impression; a blank-feed embodying a pawl-and-ratchet device 30 and means for retracting the pawl varying distances to make variable-length feed strokes; and a series of feed faces connected for operation in consonance with said impression devices and having working positions 35 corresponding to the line-space values, respectively, of said impression devices.

154. In a typographic machine, the combination with a series of selective impression devices and a carrier upon which said impression devices are mounted, of means for 40 actuating said carrier to bring selected devices one at a time to the working point of the machine; means for sustaining a blank to be operated upon at the working point; 45 means for impressing the blank and the particular impression device selected one upon the other to make an impression; a blank-feed embodying a pawl-and-ratchet device organized for making variable-length feed 50 strokes; and a series of feed faces connected for operation in consonance with said impression devices and having working positions corresponding to the line-space values, respectively, of said impression devices.

55 155. In a typographic machine, the combination with a series of selective impression devices, of means for conveying such devices periodically past the working point of the machine; means for sustaining a 60 blank to be operated upon at the working point; means for impressing the blank and the particular impression device selected one upon the other to make an impression; a blank-feed embodying a pawl-and-ratchet

device organized for making variable-length feed strokes; and a series of feed faces connected for operation in consonance with said impression devices and having working positions corresponding to the line-space values, respectively, of said impression devices.

156. In a typographic machine, the combination with a series of selective impression devices, of means for bringing selected devices one at a time to the working point of the machine; means for preliminarily cross-slitting the blank to form a flowage space at the side of the respective type-blanks; means for impressing the blank and the particular impression device selected one upon the other to make an impression; a blank-feed embodying a pawl-and-ratchet device organized for making variable-length feed strokes; and a series of feed faces connected for operation in consonance with said impression devices and having working positions corresponding to the line-space values, respectively, of said impression devices.

157. In a typographic machine, the combination with a series of selective impression devices, of means for bringing selected devices one at a time to the working point of the machine; means for preliminarily cross-slitting the blank to form a flowage space at the side of the respective type-blanks and for trimming a type-blank to a shape approximating to that of the type-block to be made therefrom; means for impressing the blank and the particular impression device selected one upon the other to make an impression; a blank-feed embodying a pawl-and-ratchet device organized for making variable-length feed strokes; and a series of feed faces connected for operation in consonance with said impression devices and having working positions corresponding to the line-space values, respectively, of said impression devices.

158. In a typographic machine, the combination with a series of selective impression devices, of means for bringing selected devices one at a time to the working point of the machine; means for sustaining a blank to be operated upon at the working point; means for rolling the blank and the particular impression device selected, the one across the other to make an impression; and a feed face connected for operation in consonance with a selected impression device and in a working position which serves to control the position assumed by the selected impression device during its working.

159. In a machine organized for making impressions in succession, the combination with a carrier, of at least one subordinate carrier mounted thereon, and provided with a plurality of selective impression devices; means for actuating the main carrier and

ing to the die-carrier a rapid continuously progressive rolling movement toward and upon a blank in said support, and means for feeding the blank support and die one relative to the other at a speed sufficiently rapid to mechanically generate sufficient heat to reduce the molecular cohesion of the blank-particles.

188. The combination with means for preliminarily preparing the edge of a typebar-blank, of a die for impressing such preliminarily prepared portion and forming therein a type, and means for effecting a rapid working engagement between the die and the preliminarily prepared portion of the blank whereby the blank is heated and the action of the die in forming the type facilitated.

189. In a key-controlled machine, the combination with type-making mechanism embodying a die-carrier, type-forming dies thereon, and reducing means for removing material from one point in the typebar blank without adding it to the mass at an adjacent point, of a support for the typebar-blank, and means for actuating one of the type-making members in a curvilinear path relatively to the other to effect a rapid rolling engagement between the typebar-blank and the die, and the heating of the material of the blank.

190. The combination with a type-making mechanism, embodying a die-carrier, type-dies, and reducing means for removing material from one point in the typebar-blank without adding it to the mass at an adjacent point, of a support for the typebar-blank, and means for actuating one of the type-making members relatively to the other in a curvilinear path to effect a rapid rolling engagement between the blank and the type-die and thereby displace a portion of the blank in the direction of such rolling movement and heat the material of the blank.

191. The combination with mechanism for effecting a rapid working engagement between a type-forming tool and a typebar-blank, of means for imparting to the blank a feed movement in the direction of its length, a plurality of type-forming tools, and means for selectively actuating said tools in cycloidal paths each to a working point.

192. The combination with a blank-carrier, of a tool operative for shaping a portion of the face of the blank, means for normally revolving said tool in an inoperative relation with said blank, and means for intermittently actuating one of said members to effect a rapid working engagement between the tool and the blank.

193. The combination in a type-making mechanism, embodying reducing means for removing material from one point in the typebar-blank without adding it to the mass at an adjacent point, of feeding mechanism controlled by said type-making mechanism and adapted for intermittently feeding the typebar-blank and presenting successive blank segments of said blank to the type-making mechanism, and means for operating said type-making mechanism at a high rate of speed whereby the material of the blank is heated and the formation of a type facilitated.

194. The combination with means for supporting a blank, of a pair of corresponding separately-movable character-shaping tools, and means for rapidly actuating said tools in cycloidal paths into and out of engagement with a portion of a blank.

195. The combination with means for supporting a blank, of corresponding separately-movable shaping tools, and means for successively and rapidly actuating said tools respectively in prolate and curtate hypocycloidal paths into and out of engagement with a blank.

196. The combination with a blank and means for supporting the same, of a tool operative for shaping a portion of the face of the blank, means for normally revolving said tool in inoperative relation with said blank, and means for intermittently carrying said tool into rapid working engagement with the blank.

197. The combination with a plurality of selective type-dies, of mechanism for rolling a blank and the dies against each other with sufficient rapidity to effect the heating of the blank and thereby facilitate the production of the types.

198. The combination with a blank and means for supporting the same, of means operative for shaping a portion of the blank, means for revolving said shaping means in operative relation with said blank, and means for intermittently carrying said blank in working engagement with the shaping means with sufficient rapidity to generate heat.

199. In type-making mechanism, the combination of type-forming instrumentalities for operating upon the edge of the blank and means for rapidly actuating the same to generate heat and reduce the molecular cohesion of the particles of the type-blank.
